KNITTING MACHINE

Max C. Miller, Cumberland, R. I.

Application February 28, 1936, Serial No. 66,207

37 Claims. (CL. 66—82)

The present invention relates to flat full-fashioned hosiery machines.

It is a principal object of the present invention to provide a novel and improved machine of this description which is well adapted for the knitting of a complete full-fashioned stocking blank including the welt, leg and foot portions thereof as a substantially continuous knitting operation upon the one machine.

It is a further object of the invention to provide in a flat full-fashioned machine of this general description, a simple and efficient mechanism to remove and to support the needle instep loops clear of the needles during the formation of the heel flap portions of the stocking blank, and thereafter to return the loops to the needles for the continued knitting of the foot and toe portions of the stocking blank.

It is another object of the invention to provide in a foot and leg machine of this description including mechanisms for forming the welt and for supporting the instep fabric, supporting and actuating devices for these mechanisms to form simple and efficient operating units which may be readily assembled upon machines of existing types.

It is another object of the invention to provide in a machine of this general description, knock-over and webholder elements having a take-up action to clear the fabric to the backs of the needles, together with actuating means for causing these elements to cooperate in a novel and effective manner with the needles and the cooperating knitting devices during the performance of the various knitting and transfer operations by the machine to produce a complete full-fashioned stocking blank.

It is a further object of the invention to modify and improve certain of the actuating and control mechanisms for the machine to secure a more efficient and fully automatic operation of the several cooperating knitting devices for the production of complete full-fashioned stocking blanks.

With these and other objects in view as may hereinafter appear, one feature of the invention consists in the provision with an instep fabric supporting bar comprising a series of loop lifting implements, of novel actuating mechanism therefor which is well adapted for imparting a series of positioning movements to the instep bar to lift from the needles and to support the instep needle loops beyond the back line of the needles during the knitting of the needle flaps,

and thereafter to return the instep loops to the needles.

Another feature of the invention consists in the provision of a single supporting structure for the welt bar and instep bar associated with each section of the machine, which in the preferred form of the invention takes the form of a hanging frame or pendant supported on a vertically movable pivot directly above the needles, together with means for substituting one or the other of said bars in operating position.

Another feature of the invention consists in the provision of separate welt and instep bar actuating devices for controlling the movements of the hanging frames or pendants associated with the several sections, and the welt and instep bars supported thereon, to perform successively the operations of forming the welt, and of removing from and returning the instep fabric loops to the needle.

In accordance with another feature of the invention, control mechanisms are provided for controlling the operation of the notched knock-over and webholder elements of the present machine to secure the necessary cooperation thereof with the needles and associated operating instrumentalities for turning the welt, for taking up and forcing the fabric along the backs of the needles during normal knitting and narrowing operation, for the setting up of raw edges of fabric loops, and for assisting in the operation of the instep bar both to remove and to return the instep needle loops to the needles.

The features of the invention consist also in the devices, combination and arrangement of parts hereinafter described and claimed which, together with the advantages to be obtained thereby, will be readily understood by one skilled in the art from the following description taken in connection with the accompanying drawings, in which Fig. 1 is a view in front elevation of a multiple section flat full-fashioned foot and leg knitting machine, only so much of the machine being shown as is necessary to illustrate the connection of the present invention therewith; Fig. 2 is a sectional view taken on the line 2—2 of Fig. 1, certain of the cams on the shaft 270 having been removed; Fig. 3 is a detail sectional view taken on the line 3—3 of Fig. 1, illustrating on an enlarged scale the several knockover element actuating cams; Fig. 4 is a detail sectional view taken on the line 4—4 of Fig. 1, illustrating on an enlarged scale a portion of the up and down cam motion for the instep bar; Fig. 5 is a detail sectional view taken on the line 5—5 of Fig. 2,

illustrating on an enlarged scale the needle bar, the knockover bit bar and the narrowing frame including leg and foot narrowing points; Fig. 6 is a diagrammatic view of the complete stocking blank as it appears when cast off from the needles; Fig. 7 is a view similar to Fig. 6, illustrating the stocking blank after the operation of looping the side portions of the heel flaps to the newly set up portions of the sole fabric. Fig. 8 is a detail sectional view in front elevation and on an enlarged scale, illustrating particularly welt and instep bars and a portion of the hanging frame supporting the same; Fig. 9 is a sectional view taken on the line 9—9 of Fig. 8; Fig. 10 is an end view looking from the left, of the parts shown in Fig. 8; Fig. 11 is a view similar to Fig. 10, but with the positions of the welt and instep bars reversed to position the welt bar in operating position on the hanging frame; Fig. 12 is an enlarged detail view of the pattern chain controlled levers illustrated in Fig. 1; Fig. 13 is an end view looking from the left illustrating substantially the parts shown in Fig. 12; Fig. 14 is a sectional plan view taken on the line 14—14 of Fig. 12; Fig. 15 is a detail view looking from the right taken substantially on the line 15—15 of Fig. 1, illustrating particularly a portion of the control mechanism for shifting the instep bar actuating cams into and out of operation; Fig. 16 is a detail plan view of the right hand end of the machine table shown in Fig. 1, illustrating particularly a portion of the control mechanism for determining the position of the several instep bars of the machine lengthwise of the needle series; Fig. 17 is an end view of the parts shown in Fig. 16, showing additionally the instep bar guide members; Figs. 18 to 33 inclusive, are a series of somewhat diagrammatic views illustrating the relative positions of the instep loop lifting instrumentalities and the cooperating needles, sinkers and webholder elements during the successive steps in the operation of removing the instep needle loops from the needles, and the subsequent return of these loops to the needles after the knitting of the heel flap portion of the fabric; Figs. 34 to 37 inclusive, are somewhat diagrammatic sectional views of the subsidiary cam shaft, illustrating the relative positions of the instep bar actuating cams and the mechanism for shifting these cams, Fig. 34 being taken on the line 34—34 of Fig. 1, to illustrate particularly the position of the cam for moving the instep bar vertically to remove the instep loops from the needles just prior to the shifting of said cam into operating position, Fig. 35 being a view taken on the line 35—35 of Fig. 1, to illustrate particularly the cooperating cam for imparting forward and back movements to the instep bar for a position of the shifting mechanism shown in Fig. 34, Fig. 36 being a sectional view taken on the line 36—36 of Fig. 1, illustrating the position of the cam for moving the instep bar vertically to return the loops to the needles in a position just prior to the shifting of this cam into operating position, Fig. 37 being a sectional view taken on the line 37—37 of Fig. 1, to illustrate the cooperating cam for moving the point bar forward and back in a position corresponding to that illustrated in Fig. 36; Figs. 38 to 55 inclusive, are a series of somewhat diagrammatic views showing the cooperative relationships of the needles, sinkers and knockover elements in succeeding steps during the setting up of a raw edge of fabric on the needles and during the subsequent knitting of a plurality of suc-

ceeding courses; Fig. 56 is a detail sectional view taken on the line 56—56 of Fig. 1, to illustrate particularly the cooperative relationships of the webholder element cam lever and the control mechanism therefor; Figs. 57 to 59 inclusive are a series of similar views in front elevation showing the parts illustrated in Fig. 56 for three successive positions of the knockover element cam roll during the operation of setting up a raw edge of fabric and knitting a plurality of succeeding courses; Fig. 60 is an enlarged view of a welt hook; Fig. 61 is a sectional view taken on a line 61—61 of Figure 1, illustrating a modified or more complete form of applicant's invention; Fig. 62 is a view in front elevation of the parts shown in the upper portion of Fig. 61; Figs. 63 and 64 illustrate respectively in front and side elevation a specific form of loop lifting implement; Fig. 65 is a sectional view taken on a line 65—65 of Fig. 63 illustrating the operation of the improved loop lifting point to maintain the fabric loops on the points and corresponds specifically to the position of these elements illustrated, for instance, in Fig. 28; and Fig. 66 is a similar sectional view, taken through applicant's improved loop lifting point and the needle cooperating therewith during the transfer operation, and corresponds to the position of these parts illustrated specifically in Fig. 32.

30 The machine illustrated in the drawings is a multiple section flat full-fashioned machine of ordinary description having a series of supporting frames such as that shown at 66 in Fig. 1 which are spaced along the length of the machine and serve as bearing supports for the various shafts and rods for controlling the several knitting devices of the machine. The frames are rigidly connected together by the usual work table 65 and supporting rails such as indicated for instance at 67 and 68 in Fig. 2.

35 The knitting instrumentalities for each knitting section of the machine include a series of spring beard needles 69 which are movable as a unit and have imparted thereto the usual vertical and forward and back or in and out positioning movements with relation to a fixed press edge 70, cooperating yarn measuring sinkers 71 having the usual construction and mode of operation of these elements, and cooperating

40 knockover and webholder elements 72 which are constructed and arranged to perform the usual functions of these elements in a new and more efficient manner and also to perform certain additional functions as hereinafter described, and also as set forth in part in applicant's pending application Serial No. 59,236, filed January 15, 1936.

45 The needles 69 for the several sections of the machine are carried on needle bars 73 (Figs. 1, 2 and 5) which are pivotally supported in the usual manner on horizontal lever arms 74 secured to a rock shaft 75 extending the length of the machine. Vertical movements are imparted to the needles by means of one or more downwardly extending cam levers such as that indicated at 76 in Figs. 1 and 2, rigidly secured at its upper end to the rock shaft 75, and provided at its lower end with a cam roll 77 for engagement alternatively with the usual knitting cam

50 78 and narrowing cam 79 on the main cam shaft 80 of the machine. Forward and back movements are imparted to the needles through the usual connections which include downwardly extending lever arms 81 secured to the needle bars

55 73 which are connected by means of links 82 to

lever arms 83 secured to a rock shaft 84 extending the length of the machine. Certain of the levers 83 are provided with downward extensions such as that indicated at 85 provided with a cam roll 86 for engagement alternatively with the usual knitting cam 87 and narrowing cam 88. Inasmuch as the supporting and actuating connections for the needles 69 and sinkers 71 are well known in the art and have the usual mode of operation for both knitting and narrowing, no further description thereof is believed necessary.

The knockover and webholder elements employed with the present machine, have substantially the construction set forth in applicant's copending application Serial No. 59,236 above referred to, being provided with two substantially parallel knockover surfaces at slightly different levels separated by a yarn engaging throat in the form of an undercut notch. These knockover elements are maintained under an adjusted spring pressure in a normally raised position closely adjacent the under side of the sinkers, and are arranged for forward and back movements with relation to the needles during the knitting of each succeeding course to engage in the throats and to position the sinker loops of the previously knitted course beyond the back line of the needles during the knocking over of the new loops on the inner or raised knockover surfaces. With this construction and mode of operation of the knockover elements during normal knitting, as above set forth, and as more fully described in applicant's copending application Serial No. 59,236 above referred to, the knockover elements operate as a fabric take-up to surely and accurately position the needle loops of the previously knitted course beyond the back line of the needles prior to and during the subsequent rising movements of the needles, and serve, therefore, to take the place of the fabric take-up mechanism ordinarily employed in full-fashioned machines of this general description.

The knockover and webholder elements 72 for each section of the machine are rigidly secured to a knockover bar or support 89 (Figs. 2 and 5) which is pivotally supported at each end on support levers 90 loosely sleeved on a supporting rock shaft 91 of the machine. There is also secured to each knockover bit bar 89, a downwardly extending lever arm 92 which is acted upon at its lower end by means of a tension spring 93 to maintain the lever 92 in engagement with an adjustable stop screw 94 carried on one of the supporting lever arms 90 to maintain the knockover elements yieldingly in a raised position adjacent the under side of the sinkers. As in applicant's copending application Serial No. 59,236 above referred to, forward and back movements are imparted to the supporting lever arms 90 and the knockover elements 72 through connections which include an upwardly extending actuating lever 98 rigidly secured to the rock shaft 91, one such lever preferably being provided at each end of each section, and a downwardly extending cam lever 100 also secured to the rock shaft 91. A tension spring 102 connected at one end to the lever arm 98 and at its other end to the supporting lever 90, tends to maintain the supporting levers 90 and knockover elements in a relatively forward position determined by the engagement of an adjustable stop screw 104 on the lever arm 98 with a corresponding abutment 106 formed integrally with the lever arm 90. The cam lever

100 is provided at its lower end with a transversely extending pin 108 on which is supported an axially shiftable cam roller 110 arranged for engagement alternatively with any one of several actuating cams on the main cam shaft 80, including a knitting cam 112, a narrowing cam 114, and a fabric set-up cam or disk 116 (see Figs. 1, 3 and 57 to 59 inclusive).

The position of the knockover bit operating roller 110 on the pin 108 is controlled by means of a cam roll shift member 118 (see Figs. 1, 2, and 56 to 59 inclusive) which is rigidly secured to a shift bar 120 extending the length of the machine, and is forked at its lower end to engage the cam roll 110. A tension spring 122 connected at one end to a pin on the shift bar 120 and at its other end to one of the frames 66, tends normally to hold the shift bar and cam roll 110 in a position to the extreme left which is determined by the engagement of a lug 124 on the shift bar with the upper end of a pattern chain actuated lever 126 (see Figs. 1, 12, 13 and 14) which is supported on a pivot shaft 128 mounted on a bracket 129, and is provided at its lower end with a pattern chain engaging arm 130. With the parts in the position generally indicated in Fig. 1, the webholder cam roll 110 is engaged with the knitting cam 112. It will readily be seen that the shifting of the main cam shaft 80 to the right in accordance with the usual practice for narrowing, will cause the narrowing cam 114 to be brought into operative relationship with the roll 110.

In accordance with one feature of the present invention, mechanism is provided, controlled by the pattern mechanism through the pattern chain lever 126 and shift bar 120 above described in setting up a raw edge of fabric, to maintain the cam lever 100 in a raised position, and the knockover elements 72 controlled thereby retracted during the knitting of the initial or setting-up course, and thereafter to permit the advance of the knockover elements to engage the throated portions thereof with the sinker loops, and to maintain a continuous tensioning take-up strain against said loops during the knitting of a plurality of succeeding courses. This mechanism comprises a latch member 132 secured to the shift bar 120, and arranged upon the shifting of the bar to the right, to engage beneath a corresponding abutment 134 formed on the end of the webholder cam lever 100. The timing in the step-by-step advance of the pattern chain 135 which is constructed and arranged to operate in the usual manner, is such as to cause a bump formed thereon to engage with the pattern shift lever 126 to shift the bar 120 to the right when the cam roll 110 is engaged upon the high portion of the knitting cam 112 substantially at the point designated at 138 in Fig. 2, so that the latch member 132 is caused to move under the abutment 134 as the roller 110 is moved out of alignment with the knitting cam 112. When the pattern chain is again shifted at the end of another knitting cycle, or at the completion of the initial or setting-up course of ravel sole fabric, the pattern shift lever 126 is engaged by a still higher bump on the pattern chain, causing the shift bar 120 to be moved still further to the right, so that the latch member 132 rides out from under the abutment 134 as best shown in Fig. 59, to release the cam lever 100 which falls inwardly towards the setting-up cam 116, thereby advancing the knockover elements to engage the throated portions thereof with the sinker loops. The shift

bar may be maintained in its extreme position to the right during the knitting of a plurality of subsequent courses by causing the pattern lever 126 to be engaged with a series of high bumps on the pattern chain which is advanced as above pointed out at the completion of each knitting cycle on the machine. During the course of subsequent knitting, the pattern lever 126 is permitted to return to its normal position illustrated in Figs. 1 and 12, by disengagement thereof with the high bumps on the pattern chain, and the latch 132 will pass under and beyond the abutment 134 on the webholder cam lever 100, the final shift to the left under the pressure of the spring 122 being delayed by the engagement of the roll with the side of the knitting cam 112 until a low portion thereof is reached.

The several steps in the operation of the knock-over elements 72 under the control of the setting-up cam 116 during the setting up of a raw edge of fabric and in the knitting of a plurality of subsequent courses, is illustrated in the diagrammatic views Figs. 38 to 55 inclusive, of the drawings.

Fig. 38 shows the knockover bits as they will normally be engaged with the sinker loops and with the needles 69 pulled down almost to their lowest position during the press-off of the previously knitted fabric as, for instance, would be the case prior to the knitting of the initial ravel courses of sole fabric in accordance with the mode of operation in the knitting of a full-fashioned stocking blank hereinafter more fully to be described. As there is no new yarn in the needle hooks, the subsequent downward movement of the needles will cast off the fabric, after which the needles return to their yarn sinking position shown in Fig. 39, the knockover bits standing between the needles with their notches considerably to the back side of the needles corresponding to the engagement of the cam roll 110 with the low portion of its knitting cam 112.

After the needles have reached their high position and prior to yarn sinking, the knockover bits are withdrawn in the customary manner as shown in Fig. 40. This figure also shows the subsequent kinking of the initial course of yarn for the new fabric around the needles, which thereafter go through their usual knitting motions as shown in Figs. 41 to 44 inclusive. While in the position shown in Fig. 44, the knockover bits would normally project through notches toward the backs of the needles, but during the setting up of the raw edge of fabric as herein described, they are prevented from so doing by the shift of the bar 120 to the right, which as above described, operates to position the latch 132 beneath the abutment 134 of the knockover cam lever 100, so that the initial course of yarn can be pulled upon the low or knockover surface of the knockover elements 72 as shown in Fig. 46. Prior to the rise of the needles preparatory to the knitting of a second course, the bar 120 is shifted still further to the right by the engagement of the pattern lever 126 with a still higher bump on the pattern chain 135, to move the latch 132 still further to the right out of engagement with the abutment 134, so releasing the cam lever 100 and roll 110 which are permitted to fall inwardly toward the setting-up cam 116, thus causing the knockover elements to move forwardly or toward the backs of the needles. The notched portions of the knockover bits are thus brought into engagement with the sinker wale kinks of the initial course of yarn as shown in 75

dotted lines in Fig. 46, the needles continuing to rise in the normal manner as shown in Fig. 47.

During the knitting of one or more subsequent courses, the rod 120 is maintained in its extreme position to the right by the engagement of the pattern lever 126 with a series of high bumps on the pattern chain, so that the knock-over bits are maintained yieldingly in an advanced position in contact with the sinker bars 10 of the initial course of yarn until a sufficient number of courses shall have been knitted to prevent possible unravelling or disintegration of the fabric structure during subsequent knitting. The subsequent steps in the knitting of the second course are particularly illustrated in Figs. 48 to 54 inclusive.

As illustrated in the drawings, the continued racking of the pattern chain 135 disengages the last of the high bumps on the pattern chain 20 from beneath the pattern lever 126, and the cam roll 110 is again moved to the left into engagement with its regular knitting cam 112 prior to the knitting of a third course. The knockover bits are thus withdrawn prior to the next yarn 25 sinking stroke of the sinkers as shown in Fig. 55, so that from this point the knockover elements continue to function in the normal manner for ordinary knitting. It will be understood that the knockover bits where found desirable in knitting 30 with certain types of yarn, may be maintained in contact with the fabric during knitting of one or more additional courses to insure the production of a sufficient amount of fabric to prevent possible unravelling of the initial courses 35 when the normal mode of operation of the knock-over bit is resumed.

There is provided with the present machine, the usual narrowing mechanism for producing the narrowings of the leg and foot portions of a full-fashioned stocking blank. Inasmuch as these mechanisms are well known in the art, it is believed that only a brief description thereof in connection with Figs. 2 and 5 of the drawings, will be necessary. This mechanism comprises 40 the usual narrowing machine in the form of a shaft 140 extending the length of the machine and supported at intervals along its length upon lever arms 142 fulcrumed on a pivot shaft 144 at the rear of the machine. A number of downwardly extending brackets or arms 146 rigidly secured to the assembly including the shaft 140 and arms 142, provide supports for a number of axially shiftable narrowing point carrier bars 148, 150, 152 and 154. Two groups of narrowing 45 points for each section designated respectively at 156 and 158 are secured respectively to the point carrier bars 148 and 152, for operation in the usual manner as selavage narrowing points for shaping the top of the leg, the calf, heel and sole. Two additional sets of narrowing points 50 for each section as designated at 160 and 162 are secured respectively to the bars 150 and 154 which operate in the usual manner to shape the toe portion of the stocking blank. There is also provided with each section the usual point knife 164.

The narrowing machine is raised and lowered to cause the several sets of narrowing points above described, to cooperate with the needles through connections which include the link 166 (Figs. 1 and 2) connected at its upper end to the narrowing machine, and at its lower end to a laterally extending cam lever 168 which is supported at its forward end on a pivot 170 and is provided intermediate its length with a cam roll

174, for cooperative engagement with the usual narrowing cams generally indicated at 176 on the main cam shaft 80 of the machine.

In order that the narrowing machine supporting the selvage and toe transfer points may be locked out of operation during the removal and return of the instep needle loops to the needles as hereinafter described, there is also provided with the present machine the usual narrowing machine locking-out mechanism which may be described briefly as follows in connection with Figs. 1 and 2 of the drawings. This mechanism takes the form of a roller lever 180 which is secured at its lower end to a shaft 182 (see Fig. 1), and is provided at its upper end with a roller 184. Also secured to the shaft 182 is a lever 186 which is connected by means of a forwardly extending link 188 to a manually operable lever 190 supported on a stationary pivot 191 and provided at its lower end with a handle 192. When the roller 184 is moved forwardly by turning the handle 192 to its dot-and-dash position (Fig. 2), it operates to engage with and lift the cam lever 168 and link 166 to a raised inoperative position in which the narrowing machine cam roller 174 will not be operated upon by the narrowing cams.

The mechanism for shifting the main cam shaft 80 axially to position the narrowing cams thereon into operative position, is generally indicated in Fig. 1 of the drawings, as comprising a shift roller 194 which is arranged for engagement with a shift cam track formed on adjacent faces of the cam disks 196 and 198 rigidly secured to the cam shaft 80. Inasmuch as this mechanism for shifting the cam shaft 80, is well known in the art, and is controlled in the usual manner from the pattern chain 135 of the machine, no further illustration thereof is believed necessary.

In accordance with the present invention, an automatic welt mechanism is provided for setting up the welt portion of the fabric on the machine, and thereafter for closing the welt, which has been particularly adapted and arranged to operate in combination with mechanism hereinafter to be described for removing from the needles and supporting the instep portion of the fabric during the knitting of the heel flaps to provide a more fully automatic machine which is well adapted for substantially continuous operation to produce complete full-fashioned foot and leg stocking blanks. The welt mechanism herein disclosed is similar in many respects to that described and illustrated in applicant's copending application Serial No. 726,285, filed May 18, 1934.

The welt mechanism referred to, comprises a welt bar 200 for each section of the machine, each of said bars having rigidly supported thereon a series of welt hooks 202 spaced to cooperate with each alternate needle. The welt hooks are identical in their general construction and mode of operation with those set forth in applicant's copending application above referred to, but may be briefly described in connection with Fig. 60 of the drawings, in which the hook is indicated as comprising a vertically extending shank tapered at its lower end to enable the hook with certainty to pass downwardly between adjacent sinker and webholder elements in close proximity to the press edge to the beard side of the needles. There is also provided with each of these elements, a bifurcated hook 204 which is provided with tapered tip portions arranged to embrace the needle shank to permit the engage-

ment of said hooks with and the lifting of alternate needle wale kinks over the tops of the needles subsequent to the sinking of an initial course of yarn against the needle shanks by the sinkers. There is also provided at the base of each bifurcated hook, a vertically extending cam portion 206 which is arranged when the hooks and welt loops held thereon are positioned over the needles during the closing of the welt, to engage with and guide the tips of the needles upwardly through the loops held thereon.

The welt bar 200, as best shown in Figs. 8 to 11 inclusive, is slidably mounted in guideways 210 formed in a supporting frame 212 which comprises two arms pivotally mounted on two studs 214 formed on the lower end of a hanging frame or pendant 216 which provides the main support for the welt bar and also the instep bar herein-after to be described. The pendants 216, of which one is provided for each section of the machine, are secured at their upper ends to a rock shaft 218 which is supported directly above the needles at a plurality of points along its length in bearings formed in forwardly extending lever arms or hangers 220 secured to a pivot shaft 222. With this construction and arrangement of the hanging frames 216 and supporting arms or hangers 220, the frames 216 and elements supported thereon are readily movable forward and back with relation to the needles on the pivotal support provided by the rock shaft 218, and may be moved vertically with relation to the needles by the movement of the arms 220 to raise or lower the rock shaft 218.

35 In accordance with certain features of the present invention, there is also supported on each of the hanging frames 216, an instep point bar 224 which carries a series of loop lifting or transfer points 228 corresponding to the instep needles, and which is connected to the welt bar, so that either one of said bars may be moved into operating position, while at the same time the other bar is moved to an inoperative position. The instep bar is supported on two lever arms 230 of a double lever which is rigidly supported on a pivot shaft 232 which extends between the two downwardly extending side portions of the hanging frame 216, being supported at each end in bearings formed in the pivot pins 214 to permit a free rotational movement of the shaft 232 and levers 230, and also an axial movement thereof lengthwise of the needle series. In order to provide for an angular adjustment of the loop lifting points 228 in their support, the point bar 224 is connected to the levers 230 by two pivot pins 236, and is adjustably maintained in the desired angular position with relation to the lever arms 230 by means of stop screws 238 which are carried on lugs 240 on the lever arm 230, and are arranged for engagement with adjacent portions of the point bar 224 at each side of the pivotal support provided by the pins 236 to hold the point bar 224 rigidly in the desired angular position. For operatively connecting the point bar to the welt bar, there are also provided two extensions 242 of the lever arms 230 which are offset from the pivot shaft 232 in a substantially opposite direction, and are connected at their tip ends so that the lever arms 230 and 242, and pivot shaft 232, combine to form the rigid double lever unit above referred to. The lever arms 242 are adjustably connected to the slidably welt bar 200 for angular adjustment of the welt bar with relation to the instep bar 224 about the pivot studs 214 by

means of an adjustable stop screw 244 which is loosely fitted in a boss 245 formed on the adjoining ends of the levers 242, and for axial adjustment of the welt bar with relation to the instep bar lengthwise of the needle series by means of two adjustable stop screws 246 carried in lugs 248 on the welt bar for engagement with opposite sides of the assembly including the lever arms 242 and boss 245. With this construction and arrangement of the double lever comprising the arms 230 and 242, it will readily be seen that while the entire assembly including the two bars and the supporting levers therefor are free to turn about the pivotal center provided by the studs 214, the angular relationship of the two bars remains fixed. In order to permit one of the other bars to be swung freely into operating position, the hanging support 216 is constructed and arranged to provide a sufficient clearance to permit the movement of the relatively short instep bar over the pivot provided by the studs 214 and through the frame. In order to locate one or the other of said bars in operating position, a toggle spring arrangement is provided comprising tension springs 250, each of which is connected at one end to the supporting frame 212 for the welt bar, and at its upper end to an arm 252 which is rigidly secured in adjusted position on a stud 254 on the hanging frame 216. With the welt bar 200 in operating position as illustrated in Fig. 11, the spring operates upon one side of the pivot provided by the studs 214 to support the welt bar yieldingly upwardly in a limiting position determined by the engagement of stop pins 256 on the arms of the welt bar supporting frame 212 with two rearwardly extending stop levers 258 which are pivoted on the studs 214. For convenience of assembly, the stop levers 258 are provided with upwardly extending portions which are sleeved on the studs 254 to provide a rigid structure. When the positions of the welt bar and instep bar are reversed to position the instep bar in operating position, as illustrated in Fig. 10, the toggle springs 250 operate on the other side of the pivot provided by the studs 214 to move the welt bar upwardly and the instep bar downwardly against limiting stops provided by the engagement of adjustable stop screws 260 carried on the supporting frame 212 with downwardly extending stop lugs 262 formed on the upward extension of the stop levers 258 above described. The stop lugs 262 are arranged also for engagement with downwardly extending arms of the toggle spring supporting levers 252 to further support said levers. With the construction and arrangement of the parts disclosed, it will readily be seen that the toggle springs 250 perform the additional function of permitting a yielding downward movement of the welt bar and hook supported thereon when such action is desired during the knocking over of the initial or setting-up course of welt loops subsequent to the removal of the loops forming the setting-up course from the alternate needles.

The present machine is also provided with the mechanism for automatically laying in a welt wire which is similar to that specifically set forth in applicant's copending application Serial No. 726,285 above referred to, and comprises welt wire guideways 263 illustrated in Figs. 1 and 2, which are rigidly secured to the table 65, one at each side of each section. The welt wires are normally supported at the inner end of the

guideway on the tip portions of latch levers 264 against the tensioning strain of take-up straps (not shown) which may be of ordinary description, extending from opposite ends of the welt wires to the usual fabric takeup roll 265 of the machine. The welt wires are automatically released to bring them into operative engagement with the welt fabric after a sufficient amount of such fabric has been knitted, through connections which include lever arms 266 secured to a rock shaft 267, links 268 connecting the lever arms 266 to the welt wire latch levers 264, a control lever 269 and downwardly extending link 271 shown in dot-and-dash lines in Fig. 2, which are preferably operated from the pattern chain 135 of the machine, as set forth in applicant's copending application Serial No. 726,285 above referred to.

Inasmuch as it is proposed as hereinafter more fully set forth, at some point in the knitting operation subsequent to the closing of the welt, to wholly disconnect the fabric from the usual take-up roller 265 and take-up straps associated therewith, and to continue the formation of the leg and foot portions of the fabric without utilizing any take-up device other than the knockover elements 72 above described, there is provided with each section of the machine, a fabric guideway or support in the form of a flat plate 273 of a width equal to the length of the section, and extending from a point closely adjacent the under sides of the knockover elements across the table 65 of the machine, and terminating at its forward end in a downwardly curved chute to permit the convenient delivery of the stocking blanks into receptacles placed at the front of the machine.

In accordance with the present invention, mechanism is provided controlled from the pattern mechanism of the machine, for moving the hanging frames 216 and welt bars carried thereon in timed relation to the needle movements to set up and to close the welt, and similarly for moving the hanging frames 216 and instep bars 224 carried thereby to remove from the needles and support the instep needle loops during the knitting of the heel flaps, and thereafter to return the loops to the needles. This mechanism comprises a secondary cam shaft 270 which is supported in the overhead portion of the machine directly beneath the rock shaft 218, and is driven in timed relation to the main cam shaft by means of a sprocket chain 272 (see Fig. 1) which passes over a sprocket 274 on the subsidiary cam shaft 270, and over a similar sprocket 276 on the main cam shaft 80. The subsidiary cam shaft has rigidly secured thereto, two vertical motion welt cams 278 and 280 which are rendered operative respectively to control the vertical movements of the welt bar during the setting up and closing of the welt, and also two welt in and out cams 282 and 284 which are arranged to control the forward and back movements of the hanging frames and welt hooks respectively during the setting up and closing of the welt.

For controlling the forward and back and vertical movements of the hanging frames 216 and instep bars 224, two vertical motion instep cams 286 and 288 are formed on a sleeve member 289 which is keyed to rotate with but is axially movable with relation to the subsidiary cam shaft 270. Similarly, two forward and back motion instep cams 290 and 292 are provided formed on a sleeve member 294 which is similarly keyed to

rotate with and to slide axially of the subsidiary cam shaft 270. In order to control the axial position of the several instep cams above described, the subsidiary cam shaft 270 takes the form of a hollow tube within which is supported a shift rod 296 which extends the entire length of the machine, and is secured to each of the sleeve members 289 and 294 by means of cross pins extending through slots formed in the subsidiary cam shaft 270.

With the present construction, vertical movements are imparted to the hanging frames 216 and instep bars 224 alternatively from the cam 286 or 288 by means of a vertical motion cam lever 298 which is supported on the rock shaft 222 adjacent one of the supporting levers 220, and is maintained in an adjustable angular relationship thereto by means of stop screws 300 on the cam lever 298 which engage with a laterally extending pin 302 on the supporting lever 220. A cross pin 304 on a downward extension of the cam lever 298 carries two cam rolls 306 and 308 which are arranged respectively for engagement with the instep cams 286 and 288. During normal knitting, the cam lever and rolls 306 and 308 are centered between and out of engagement with both cams.

Forward and back movements are imparted to the hanging frame 216 and instep bars 224 from the actuating cams 290 and 292 above described, through connections which comprise a cam lever 310 which is rigidly secured to a rock shaft 312 toward the rear of the machine, and carries at its forward end two cam rolls 314 and 316 which are arranged for engagement respectively with the actuating cams 290 and 292. During normal operation of the machine, the cam lever 310 and rolls 314 and 316 are centered between and out of engagement with their actuating cams, as shown in Fig. 1. Also secured to the rock shaft 312 is a lever 318 provided at its lower end with a pin 320 which serves as a pivotal support for a link 322. The link 322 is provided at its forward end with a recess 324 arranged for locking engagement with a pin 326 carried on a downwardly extending lever 328 secured to the rock shaft 218 supporting the hanging frame 216. A downwardly projecting lip 329 on the end of the link 322 maintains an operative contact with the pin 326 to limit movement of the hangers 216 and lever 328 outwardly when the link is raised as hereinafter described, to disconnect the instep forward and back cam motion. There is also carried on the cross pin 320, a link control cam lever 330 which is fitted at its forward end with a pin 332 and a cam roller 334 which are arranged to engage respectively with a cam 336 and a disk 338 which are supported on a sleeve hub on the cam shaft 270, being operatively connected to the shift rod 296 for axial movements relatively to the cam shaft 270 by means of a cross pin extending through slots formed in the cam shaft 270. During normal operation of the machine, the roll 334 rides on the disk 338, the pin 332 being out of engagement with the cam 336. There is also provided on the cam lever, a downwardly extending arm provided with a stop screw 342 which engages the link 322 and operates during normal knitting when the roll 334 is engaged upon the disk 338 to maintain the link 322 in a raised position out of engagement with the pin 326. A tension spring 346 connected at one end to a stationary portion of the machine, and at its other end to a rearwardly extending arm of the link 322, tends to move the link down-

wardly into operative engagement with the pin 326.

The lever connections actuated by the welt cams above described for imparting vertical movements and forward and back movements to the hanging frames 216 and welt bars 200, are substantially identical in their construction and mode of operation with the instep actuating levers above described. Further, inasmuch as these connections are substantially identical both in construction and mode of operation with the connections illustrated in applicant's copending application Serial No. 726,285 above referred to, and do not form specifically a part of the present invention, only a brief description thereof is believed necessary in connection with Fig. 1 of the drawings, to illustrate the connection of the present invention therewith. Vertical movement is imparted to the hanging frames 216 and welt bars 200 supported thereon from the welt vertical motion cams 278 and 280, by means of a cam lever 350 (Fig. 1) which is identical with the instep vertical motion lever 298 shown in side elevation in Fig. 4, being mounted on the rock shaft 222 adjacent one of the supporting levers 220 in adjusted angular relation thereto, and provided at its outer end with two cam rolls 352 and 354 arranged for engagement respectively with the welt vertical motion cams 278 and 280. During the normal operation of the machine, the cam lever 350 and rolls 352 and 354 are centered between and out of engagement with their actuating cams. For imparting forward and back movements to the hanging frames 216 from the welt forward and back motion cams 282 and 284, there is provided a cam lever 356 which is similar to the instep forward and back motion cam lever 310 shown in Fig. 2, being rigidly secured at its rear end to the rock shaft 312, and being provided at its forward end with two cam rolls 358 and 360 arranged for engagement respectively with the welt cams 282 and 284 (see Fig. 1). During normal operation of the machine, the cam lever 356 and rolls 358 and 360 are centered between and out of engagement with their actuating cams 282 and 284. Cooperating with the welt cam lever 356, is a downwardly extending double lever comprising the arms 362 and 364 connected at their lower ends by a cross pin 366 which serves as a pivotal support for a forwardly extending link 368 having formed in the forward end thereof a recess and a downwardly extending lip arranged for engagement with a laterally extending pin in a downwardly extending lever arm 370 rigidly secured to the rock shaft 218 supporting the hanging frames 216. The link 368 is normally held in a raised inoperative position by means of a link control lever 372 pivoted on the cross pin 366 and provided with a downwardly extending arm 374 which serves as a support for an adjustable stop screw engaging with the under side of the link 368. At its forward end the control lever 372 is provided with a laterally extending pin 376 and a cam roll 378 which are arranged to cooperate respectively with a cam 380 and disk 382 rigidly secured to the cam shaft 270. During the normal operation of the machine, the roll 378 rides on the disk 382 to maintain the link 368 out of locking engagement with the lever arm 370, the pin 376 being out of engagement with the cam 380 as shown in Fig. 1. A tension spring (not shown) tends to move the link downwardly when released by the operation of the cam lever 372. The lever arms 362 and 364, link 368, lever arm 370 and cam lever 372,

are identical in construction and mode of operation with the corresponding parts for imparting the forward and back instep movements to the hanging frames 216 above described and illustrated in side elevation in Fig. 2.

The hanging frames 216 are swung yieldingly outward toward a limiting position in which the downwardly extending lip 329 engages with the pin 326 on the lever arm 328 secured to the rock shaft 218 by means of a take-up device which comprises a segmental chain supporting member 390 formed on the hub of the lever 370, to which is secured a take-up chain 392 which may be of any ordinary description as indicated in Fig. 2. This chain preferably extends rearwardly over a take-up pulley (not shown), and has secured thereto a weight which may be adjusted to secure the desired forward tensioning strain on the hanging frames 216.

In order that the supporting levers 220 for the rock shaft 218 and hanging frames 216 may be normally supported in a predetermined vertical position during the normal operation of the machine, and to permit the movement of the welt and instep vertical motion and forward and back motion cams beneath their respective actuating levers, there is provided with the present construction, a latch lever 394 which is mounted free to oscillate on a pivot rod 396, and carries a stop screw 398 arranged normally to engage beneath an extension 400 on one of the supporting levers 220. The lower end of the latch lever 394 is forked to provide two cam follower members 402 and 404, the follower member 402 being arranged to be acted upon alternatively by either of two welt mechanism trip cams 406 and 408 rigidly secured to the cam shaft 270, the follower 404 being similarly arranged to be acted upon alternatively by two instep mechanism trip cams 410 and 412 keyed to rotate with the cam shaft 270 and connected for axial movement with the shift rod by means of a cross pin extending through slotted portions in the cam shaft 270. During the normal operation of the machine, the followers 402 and 404 are centered respectively between and out of engagement with their actuating cams as shown in Fig. 1. With this construction and arrangement of the parts, it will readily be seen that an axial movement of either the cam shaft 270 or shift rod 296 in either direction to bring any one of the welt or instep vertical motion cams into alignment with the corresponding rolls on the cam levers, will cause one or the other of the follower members 402 or 404 to be aligned with the corresponding cam 406, 408, 410 or 412, to move the latch lever 394 and stop pin 398 forwardly out of engagement with the extension 400 of the supporting lever 220.

The welt and instep forward and back motion cam levers 310 and 356 are normally supported in a raised inoperative position to permit the movement of the welt and instep in and out motion cams beneath their actuating rolls by means of a rearwardly extending latch 416 (Fig. 2) pivoted on the shaft 396 and provided at its rear end with a stop screw 418 which normally engages a laterally offset lug 420 of a vertically extending lever arm 422 rigidly secured to the rock shaft 312. The position of the latch lever 416 is controlled from the latch lever 394 above described, which carries on the rearward extension thereof, a stop screw 424 arranged to engage with a lug 426 on the latch 416, being held in engagement by a tension spring 428 connected at one end to the rearward extension of the latch lever 394, and 75

at its other end to the latch lever 416. With this construction and arrangement of the parts, it will readily be seen that the forward movement of the latch lever 394 to release the welt or instep vertical motions, will simultaneously operate to depress the latch 416 to release the welt and instep forward and back motion cam levers secured to the rock shaft 312.

In accordance with the present invention, 10 mechanism is provided which is controlled from the pattern mechanism of the machine for moving the shift rod 296 axially to shift one set of instep cams into operation for moving the hangers 216 and instep bars 224 to remove the instep 15 needle loops from the needles, and for again moving the shift rod 296 to render the alternative set of instep cams operative for returning the instep loops to the needles after the completion of the heel fabric. The mechanism for controlling the axial position of the shift rod 296 comprises a shift cam lever 430 which is supported on a pivot shaft 432, and at its upper end is provided with a cam roller 434 which is arranged to cooperate with any one of three 20 shift cam tracks formed on the adjacent faces of cam disks 435 and 436 formed integrally with a sleeve 438 which is keyed to rotate with the cam shaft 270, and is connected by means of a cross pin extending through slots in the cam 25 shaft for axial movement with the shift rod 296. 30

Movement of the shift cam lever 430 and shift roll 434 inwardly a relatively small distance toward the axis of the cam shaft 270, causes the roll to engage with cooperating face cam 35 surfaces forming a shift cam track 440 to move the assembly including the cam disks 435 and 436 to the left, thus causing the instep cams 288 and 292 to move beneath their follower rolls 308 and 316 respectively, and at the same time causing 40 the cam 412 to engage beneath the follower arm 404 to trip the latch lever 394 as above described. At the same time the disk 338 is moved to the left from under the roll 334, so that the link 322 is permitted to drop into locking engagement 45 with the lever arm 328 to connect the hangers 316 to the instep in and out motion as above described. At the end of nearly one complete revolution of the subsidiary cam shaft 270, the shift rod 296 is moved to the right to its initial position when the shift lever 430 again moves outwardly to engage the shift roll 434 in a neutralizing cam track 443, thus causing the parts to be returned to their normal inoperative position shown in Figs. 1 and 2. The shift lever 430 and shift roll 434 are moved positively away from the cam shaft 270 to neutral position by the engagement of a roll 442 on the shift lever with a cam 444 formed on the periphery of the cam disk 436.

Movement of the shift cam lever 430 and shift roll 434 a relatively greater distance toward the axis of the cam shaft 270, operates to engage the roll between the cooperating face cam surfaces forming the shift cam track 446 on the adjacent faces of the cam disks 435 and 436 to move the assembly including the disks 435 and 436 and shift rod 296 to the right, thus causing the instep cams 290 and 286 to be positioned respectively beneath their rolls 314 and 306, and the cam 410 to be positioned beneath the follower member 404 to disengage the latch lever 394 as above described. At the same time the disk 338 is shifted from under the roll 334 of the link control lever 330, to permit the dropping of the link 322 into locking engagement with the

lever 328, thus operatively connecting the hangers 216 to the instep in and out motion. At the end of substantially one revolution of the cam shaft 270, the shift lever 430 and roll 434 are moved to neutral position in which the shift roll 434 engages in the neutralizing cam track 443 by the engagement of the cam 444 with the roll 442, so that the shift rod 296 is again moved to the left to its normal inoperative position. The position of the several cooperating parts is such as to permit the stop screws 398 to move under the extension 400 of the supporting lever 220 to lock the hangers 216 in their normal inoperative vertical position when the latch lever 394 is permitted to move inwardly as the cam 410 is returned to its inoperative position out of alignment with the follower member 404. A detailed description of the mode of operation of the instep mechanism above set forth will be found below in connection with the description of the machine operation to form a full-fashioned foot and leg stocking blank.

The mechanism through which the shift lever 430 is controlled from the pattern mechanism of the machine to effect the required shifting movements of the instep cams as above described, comprises a downwardly extending latch lever 450 secured to the pivot pin 432 to form a rigid downward extension of the shift lever 430, and a latch 452 pivotally supported at 454 on the machine frame, the latch being arranged for abutting engagement with the end portion of the latch lever 450, or with one of two successively raised steps 454' or 456 as best shown in Fig. 15 of the drawings. A tension spring 458 connected at one end to the latch 452 and at its other end to the table of the machine, tends normally to maintain the latch in a fully depressed position for engagement with the end portion of the latch lever 450. The position of the latch 452 is directly controlled from the pattern chain of the machine through connections which include a downwardly extending link 460 connected at its upper end to a forward extension of the latch 452 and at its other end to one end of a bell-crank lever 462, the other arm of which is connected by means of a long link 464 to a pattern chain lever 466 which is loosely mounted to turn on the pivot 128, and is provided with a pattern bump engaging extension 468 (see Figs. 12 to 14 inclusive).

With this construction and arrangement of the pattern mechanism for controlling the position of the instep shift lever 430, it will readily be seen that the engagement of the extension 468 of the pattern lever 466 with a relatively low bump on the pattern chain such as indicated at 469 in Fig. 12, will operate through the connections above described, to raise the latch 452 a relatively small distance against the pressure of its spring 458, permitting the shift lever 430 to fall inwardly to a position determined by the engagement of the latch with the step 454' to position the shaft 434 in engagement with the shift cam track 440 above described. Similarly, the engagement of the pattern chain lever 466 with a relatively high bump on the pattern chain such as indicated at 471 in Fig. 12, will operate to lift the latch 452 a relatively greater distance, causing the shift lever 430 to fall inwardly to a position determined by the engagement of the latch with the step 456 to position the shift roll 434 for engagement with the shift cam track 446.

In order to prevent inadvertent unlatching of

the instep cam shift mechanism, a locking device is provided which comprises a lock lever 470 which is supported on a pivot 472 and normally contacts with an abutment 473 on the chain lever 466. The locking lever 470 is connected at its rear end by means of a link 474 to one arm of a bell-crank 476 carried on the pivot shaft 128 and provided at its other end with a bump engaging extension 478. A tension spring 480 connected at one end to the locking lever 470 and at its other end to a lug on the supporting bracket 129, tends to maintain the locking lever 470 in a locking position determined by the engagement of a stop screw 482 on a laterally extending arm 483 on the bracket 129 with the rearward extension of the bell-crank 476. The bump engaging extension 478 of the bell-crank 476, is arranged to engage with an instep control bump on the pattern chain slightly in advance of the engagement thereby with the extension 468 of the pattern chain lever 466 to rock the lever 476 and locking lever 470 against the tension of the spring 480 out of alignment with the abutment 474 prior to the movement of the pattern chain lever 466. When the pattern chain lever 466 is again permitted to move to the right to its normal inoperative position, the locking lever 470 will be permitted at the same time to return to the locking position shown in Fig. 12, under the influence of its spring 480.

There is provided with the present construction, a novel and improved mechanism for aligning the hooks of the welt bar 200 with the needles during the operations of setting up and closing the welt, and also for the positioning of the points of the instep bar 224 lengthwise of the needle series during the operations of removing and returning the instep loops to the needles subsequent to the knitting of the heel flaps. To this end, two guide plates 490 are secured one to each end of the welt bar 200, which are arranged for operative engagement with stationary stop screws 492 carried on the welt wire guideway 263 (see Figs. 1 and 2) during the movement of the hangers 216 and welt bars 200 supported thereon into and out of operative engagement with the needles. This mechanism as thus far described, is substantially similar to that set forth in applicant's copending application Serial No. 726,285, above referred to, and is therefore believed to need no further illustration. With the present construction there are also provided for each section of the machine, stop levers 494 which are rigidly secured to a rock shaft 496 supported on the table 65 of the machine, and are provided with surfaces for guiding engagement with the end plates 490 of the welt bar at each end of each section when the instep bar 224 is in operating position as shown in Fig. 10, to position the assembly including the welt bar 200, the arms 242 and 230 of the double lever, and the instep bar 224 lengthwise during the movement of the hangers 216 and instep bars 200 into and out of cooperating relationship to the needles. In accordance with the mode of operation, the transfer points on the instep bar 224, as hereinafter more fully set forth, are first positioned in alignment with the needles to position the instep loops thereon, are then moved one-half a needle index to permit the points to pass between the needles, and are finally again aligned with the needles for the subsequent operation of returning the loops thereto. With the present construction, the indexing movements above referred to, are secured by an endwise shift

of the rock shaft 496 through mechanism which operates in timed relation to the instep cams and cam shaft 270 to swing the levers upwardly from the inoperative position shown in full lines in Figs. 2 and 17, to an intermediate position as indicated in dotted lines in the path of the guide plates 490 to align the points with the needles, and thereafter to the extreme high position also indicated in dotted lines with the simultaneous endwise shift of the rock shaft 496 toward the right end of the machine one-half a needle index. This shifting movement of the rock shaft is secured by means of two cooperating cam surfaces formed respectively on a supporting bracket 500 for the rock shaft 496, and on a collar 502 secured thereto (see Fig. 16). A tension spring 503 connected at one end to the rock shaft 496 and at its other end to the table 65, operates to maintain the rock shaft axially to the left with the cam surfaces referred to in operating engagement. The rocking movements are imparted to the shaft 496 and the lever arms 494 secured thereto through connections which comprise a lever arm 504 secured to the right hand end of the rock shaft 496, a link 506 connected at one end to the lever 504 and at its other end to a cam actuating lever 508 loosely mounted to turn on the shaft 312. A tension spring 510 connected to a rearwardly extending arm 512 formed on the sleeve hub of the cam lever 508, tends normally to maintain the cam lever 508, link 506 and lever 504 in a normally depressed position determined by the engagement of the lever arm 504 with an abutment 514 on the end of the table 65. A laterally extending lug 516 on the cam lever 508 is arranged upon the shifting of the assembly including the cam disks 435 and 436 and shift rod 296 to the right for operative engagement with a cam 518 (see Fig. 35) formed on the outer face of the cam disk 436, and operates first to rock the shaft 496 and guide levers 494 into the intermediate position above described during the movement of the points on the instep bar 224 to remove the instep loops from the needles, and thereafter to rock the shaft 496 and guide levers 494 to the high position described, with a simultaneous shift of the rod to the right to shift the points one-half a needle index for the movement of the points forwardly between the needles, in accordance with the mode of operation herein-after described. As the cam lever 508 now rides off the high portion of the cam 518, the cam lever is permitted to fall to its intermediate position under the influence of the spring 510 where it is held by the engagement of a latch 520 loosely mounted on the shaft 222 with an upward extension 522 formed on the sleeve hub of the cam lever 508, thus returning the points on the instep bar into alignment with the needles, in which position they remain during the subsequent knitting and return of the loops to the needles. In order to trip the latch 520 and permit the return of the rock shaft 496 and guide levers 494 to the normal inoperative position shown in full lines in Figs. 2 and 17, a pin 526 is formed on the outer face of the left hand cam disk 435 which is arranged upon the shifting of the assembly including the disks 435 and 436 and shift rod 296 to the left, for engagement with a trip lever 528 formed on the sleeve hub of the latch 520 to lift the latch out of engagement with the extension 522 of the cam lever 508. A tension spring 530 connected to the forwardly extending arm formed on the sleeve hub of the latch lever 528, tends

normally to maintain the latch in operative position.

With the present construction there is also provided at the left hand end of the machine generally illustrated in Fig. 1, a pattern control mechanism for axially shifting the cam shaft 270 to render each of the two sets of welt cams operative to impart the required movements to the pendants 216 and welt bar 200 to set up an initial course of welt fabric, and thereafter to close the welt. Inasmuch as the shift mechanism employed is substantially identical with that illustrated in applicant's copending application Serial No. 726,285 above referred to, and has substantially the same mode of operation, it is believed that a brief description thereof will be sufficient. As best shown in Fig. 1, the shift mechanism employed comprises a shift lever 540 rigidly secured to a pivot pin 542, and provided at its upper end with a shift roll 544 which normally engages with a neutralizing cam track 545 and is arranged also for engagement alternatively with either of two concentric welt shift cam tracks 546 and 548 formed on the adjacent faces of two cam disks 550 and 552 rigidly secured to the cam shaft 270. A cam roll 554 on the shift lever 540 is arranged for engagement with a cam 556 formed on the periphery of the cam disk 552 to move the shift lever outwardly to inoperative or neutralizing position at the end of each shifting and return movement of the cam shaft, to set up or to close the welt. For moving the shift lever 540 inwardly into operative engagement with one or the other of the shift cam tracks 546 and 548 above referred to, a latch lever 558 is rigidly secured to the pivot pin 542 to move as a unit with the shift lever 540, being acted upon by a latch member 560 supported on a stationary pivot 562 as generally indicated in Fig. 1. The latch lever 558 and latch 560 are identical in construction with the latch lever 450 and latch 552 illustrated in side elevation in Fig. 15, and are therefore believed to need no further illustration.

The position of the latch lever 560 is controlled through connections from the pattern chain 135 of the machine, which operate when engaged by a high bump such as that designated at 471 on the pattern chain, to rock the latch 560 sufficiently to permit the movement of the shift lever 540 and roll 544 inwardly into engagement with the inner cam track 548 to shift the cam shaft 270 to the right. This movement of the cam shaft operates to bring the welt vertical motion cam 278 beneath its roller 352, the in and out motion cam 282 beneath its roller 358, to move the disk 382 out of alignment with the in and out motion link cam lever 372 for connecting the in and out motion, and to position the cam 406 in alignment with the follower 402 of the latch lever 394 to unlock the welt vertical and forward and back cam motions. At the completion of the welt setting-up operation, and as the cam shaft 270 nears the completion of one complete revolution, the shift lever 540 and roll 544 are again moved outwardly into alignment with the neutralizing cam path 545 by the engagement of the roll 554 on the shift lever with the cam 556, thus causing the cam shaft 270 to be shifted again to the left to its neutral position. At this time the connecting link 368 of the welt forward and back cam motion will have been disconnected by the engagement of the roll 378 thereon with the cam 382 as above set forth, leaving the pendants 216 and welt bars 200 free to follow the

in and out movement of the needles under the influence of the take-up tensioning strap 392.

The welt mechanism is again thrown into operation to close the welt by means of a relatively low bump on the pattern chain such as that indicated at 469 in Fig. 12, which operates through connections hereinafter described, to move the latch lever 560 so that the shift lever 540 and roll 544 are moved a relatively small distance into engagement with the cam track 546, causing the cam shaft 270 to be shifted to the left. This movement of the cam shaft 270 causes the welt vertical motion cam 280 to be aligned with the actuating roller 354, the welt in and out motion cam 284 to be aligned with its co-operating roller 360, the disk 382 to be again disconnected from the welt forward and back motion link cam lever 372, and the cam 408 to be engaged beneath the left follower 402 of the latch lever 394 to release the welt vertical and forward and back cam motions. At the end of the welt transfer or closing operation, and as the cam shaft 270 nears the completion of one revolution, the shift lever 540 and roll 544 are again moved outwardly into engagement with the neutralizing cam track 545 to return the cam shaft 270 axially to its neutral inoperative position.

The connections through which actuating movements are imparted to the latch 560, as best seen in Figs. 1 and 12 to 14 inclusive, comprise a link 564 connected at its upper end to the forwardly extending portion of the latch 560, and at its lower end to the laterally extending arm of a pattern chain lever 566 supported to turn on the rock shaft 128, and provided on the other arm thereof with a bump engaging portion 568. The pattern chain lever 566 is also provided with a downwardly extending arm 570 which is arranged to engage against an adjustable stop pin 572 carried on the supporting bracket 129, and is normally held in engagement therewith by means of a tension spring 574.

In order to prevent the inadvertent operation of the welt cam shift mechanism above described, as for example, by the accidental operation of the latch 560, there is provided with the present construction, a safety locking device for the shift mechanism which is arranged to be released by the operation of the pattern chain only when it is desired to effect a shift of the welt cams. This mechanism comprises a safety lever 576 which is supported on a pivot 578, and is arranged at its upper end to engage beneath a pin 580 on the link 564 to lock the link and associated parts including the latch 560 in inoperative position. The position of the safety lever 576 is controlled by means of a pattern chain lever 582 which is supported to turn on the pin 128, and is provided with a pattern bump engaging extension 584. The pattern lever 582 is connected to control the position of the safety lever 576 by means of a link 586 connected at its upper end to a rearward extension of the pattern lever 582, and at its lower end to one arm of a bell-crank 588 supported to turn on the pivot 578, and having its other arm secured to turn as a unit with the safety lever 576. A downward extension of the bell-crank 588 is acted upon by the tension spring 574 to maintain the locking assembly above described in a locking position determined by the engagement of a stop screw 590 on the laterally extending lug 483 with the upper side of the pattern lever 582. The bump engaging portion 584 of the pattern lever 582 is

arranged for engagement with the welt shift bumps on the chain slightly in advance of the welt pattern lever 566 therewith, so that the safety lever 576 will have been moved out of alignment with the pin 580 prior to the operation of the pattern mechanism to effect the desired shift of the welt cams. The movement of the bump out of engagement with the pattern levers 566 and 582, will again permit the parts to return to their initial inoperative position with the safety lever 576 in locking position beneath the pin 580 under the influence of the spring 574.

With the present construction, the pattern lever 566 is operatively connected to the loose course and stitch regulator mechanisms of the machine so that the operation of the pattern lever to effect the shifting of the welt cams for setting up the welt portion of the fabric, will act simultaneously to effect an adjustment of these mechanisms to produce a loose setting-up course. Inasmuch as the specific construction and operation of the stitch regulator and loose course mechanisms to produce the desired needle movements during the knitting of the setting-up course, are fully illustrated in applicant's copending application Serial No. 726,285 above referred to, and forms specifically no part of the present invention, only a brief description of these parts is believed necessary. As shown in Fig. 1, the present machine is provided with the usual stitch adjusting or regulator mechanism comprising the rock shaft 600 to which is secured a number of identical levers 602 adapted to engage with the downwardly extending tips of the usual cam levers 85 for imparting the forward and back movements to the needles with relation to the press. The rock shaft 600 is turned on its axis to engage the levers 602 with the needle actuating levers 85 to locate the needles laterally with relation to the press edge during the yarn sinking operation to measure the length of stitch by means of the usual stitch regulator cam 604 on the main cam shaft 80 and connections actuated thereby including the usual cam lever 606 loosely pivoted on the rock shaft 600 and actuating lever 608 secured to the rock shaft 600 provided with an adjustable contact screw 610. Also secured to the rock shaft 600 is the loose stitch cam lever 612 which carries a cam roll 614 axially movable into operative engagement with a loose stitch cam 616. The position of the cam roll 614 is controlled by means of the usual shift lever 618 supported on a fixed pivoted 620, the lever 618 and roll 614 being normally held in an inoperative position by means of a tension spring 622. Also as more fully set forth in applicant's copending application above referred to, there is provided with the loose stitch mechanism, a device for imparting a forward movement of the needles away from the press subsequent to the sinking of the yarn to permit the withdrawal of the welt hooks and loops held thereon above the needles. This mechanism as generally indicated in Fig. 1, comprises a lever 624 supported on the pivot 620 and provided at its free end with a thickened portion which normally extends between the stitch regulator cam lever 606 and the contacting pin 610 on the actuating lever 608. A tension spring 626 connected at one end to the lever 624 and at its other end to the loose stitch actuating lever 618 operates when the loose stitch lever 618 is moved to the right to exert an upper pressure on the lever 624 to move the free end thereof out from between

the levers 606 and 608 when the pressure between these levers is released subsequent to the sinking of the yarn, so that the needles are permitted to fall outwardly away from the press to the desired position. As in applicant's copending application above referred to, the position of the loose stitch lever 618 may be controlled from the pattern mechanism of the machine through connections which comprise a lever 628 pivoted at 630 on the front base rail 632 of the machine, and arranged at its upper end to engage with the loose stitch lever 618. A tension spring 633 connected to a downward extension of the lever 628 tends normally to maintain this lever in an inoperative position. With the present construction, this lever is directly connected to the welt pattern lever 566 by means of a link 634, so that a movement of the welt pattern lever 566 under the influence of the bump on the pattern chain 135, will tend to swing the upper end of the lever 628 to the right into operative engagement with the loose course lever 618. Further in accordance with the present construction, a sufficient amount of lost motion is provided in the movement of the lever 628, so that the operation of the pattern lever 566 by a low bump on the pattern chain will fail to operate the loose stitch lever 618. The actuation of the pattern lever 566 by a high bump on the pattern chain to shift the subsidiary cam shaft 270 to the right for the welt setting-up operation will, however, cause the lever 628 to engage with and move the loose course lever 618 and cam roll 614 to the right into operative engagement with the loose stitch cam 616, and simultaneously to exert the desired tension on the lever 624 to permit the subsequent forward movement of the needles away from the press. It will readily be seen from the above description, that the link 634 above described, provides a positive operating connection between the pattern control connections for shifting the welt cams to their setting-up position and the loose stitch mechanism of the machine which cannot fail to operate. This feature is believed to be of considerable importance, inasmuch as any failure of the loose courses to operate at this time must inevitably result in the jamming and serious injury to the machine.

The successive steps in the operation of the points 228 on the instep bar 224 in removing and returning the instep fabric loops to the needles, may be readily understood from the diagrammatic views Figs. 18 to 33 inclusive of the drawings. The first step in the operation of the points 228 to take the instep loops from the needles, is illustrated in Fig. 18, in which the points 228 are shown as having come from their idle position in a direction indicated by the arrows, to a point well above and to the beard side of the needles. The main shaft of the machine will at this time have been shifted to the right, connecting the needles 69, sinkers 71 and knockover elements 72 for operation by their narrowing cams as in normal selvage narrowing. It will be understood also that the narrowing machine is at this time locked out of operation through the actuation of the manually operable lever 190 as above described. As shown in Fig. 18, the notched portions of the knockover elements 72 are still in engagement with the sinker loops of the previously knitted course on the needles, having therefore held down the fabric in the normal manner during the rise of the needles into the narrowing position shown.

As shown in Fig. 19, the instep points 228

have moved downwardly into engagement with the needles, the knockover bits having been withdrawn through the operation of their narrowing cam 114. Fig. 20 illustrates the next step in the 5 operation, the needles and points having continued to the limit of their downward movement to position the instep needle loops on the shanks of the points. The fabric is supported at this time on the outer or lower knockover surface of the knockover elements 72. It will be understood that the heel fabric loops on each side of the instep fabric remain on their needles. Fig. 21 shows the needles and points moved upwardly with the points now disengaged from the needles 10 and their lower end slightly above the knockover bits. At this time the instep point bar 224 is shifted laterally one-half an index, so that the points can pass between and to the back sides of the needles as shown in Fig. 22. Thereafter the 15 needles and points move downwardly as shown in Fig. 23, with the points to the backs of the needles, and with the fabric engaging upon the outer or lower knockover surface of the knockover elements 72. The knockover elements 72 are now permitted to move forwardly to engage 20 their notches against the sinker bars of the last course of loops, as shown in Fig. 24, in this manner holding down the fabric as the points are again slightly raised and the needles continue 25 their upward movement preparatory for the 30 knitting of a new course as shown in Fig. 25.

From this point throughout the knitting of the heel fabrics, the instep bars 224 and pendants 216 are maintained in a predetermined vertical 35 position and are wholly disconnected from the instep in and out motion so that they are free to move forward and back with the needles under the tensioning strain of the take-up strap 392, being gradually moved forwardly away from 40 the needles during the continued knitting of the heel flaps. As the parts reach the position shown in Fig. 25, the main cam shaft 80 is again shifted to the left, so that the various knitting elements 45 are operatively connected to their knitting cams, and the needles can move into their normal position prior to couloring the next course, as shown in Fig. 26. The knockover elements 72 being now 50 operated upon by their knitting cam 112, remain engaged with the last course of loops until the end of this upward needle movement, and are thereafter withdrawn.

After sufficient heel fabric has been knitted, it is cast off the needles in the usual manner, thus releasing the pendants 216 and instep point 55 bars 224 which move to their extreme forward position under the influence of the take-up strap 392 in which the lip on the forward end of the link 322 of the instep bar forward and back motion engages against the pin 326 on the lever 328. For convenience of illustration, the heel fabrics are shown in Fig. 27 as hanging loosely. These fabrics will in fact be supported on the fabric guideway 271 above described. After the pressing off of the heel fabrics, a short length 60 of sole or ravel fabric 682 (see Fig. 6) is produced by the previously active heel needles and such additional needles as may be necessary to produce the width of sole fabrics required.

The operation of the knockover elements 72 65 in connection with their setting-up cam 116 to produce the raw edge of ravel sole fabrics has previously been described. Fig. 27 shows the positions of the cooperating elements subsequent to the knitting of the desired number of sole ravel courses 682.

The instep shift mechanism is now again rendered operative to cause the instep points 228 to return to the instep loops held thereon to the needles, the cam shaft 80 of the machine being again shifted to the right as for ordinary narrowing, and the hangers 216 being operatively connected to their vertical and in and out cam motions. During the subsequent rotation of the cam shafts 80 and 270, the instep points 228 are moved forwardly as shown in Fig. 28, while the needles following their usual narrowing motions, are moved upwardly to the dotted line position in Fig. 28. As shown in Fig. 29, the needles follow their usual narrowing movements downwardly while the points 228 are moved over the needles and downwardly as indicated by the dot-and-dash line, so that the needles and points are brought into operative engagement as the needles reach their low position (see Figs. 30 and 31). The points and needles are then moved upwardly as shown in Figs. 32 and 33, to position the instep loops on the needle shanks and out of engagement with the points. During the continued upward movement of the needles to the yarn sinking or Coulier position, the points move upwardly, forwardly and then down to their normal inoperative position as shown by the arrow in Fig. 33. After the needles have reached their high yarn sinking position, one or more yarns are fed thereto by the active needles, and thereafter the foot and toe are knitted as a continuation of the leg fabric with the heel flaps and sole ravel fabrics hanging loosely as shown in Fig. 33, or conveniently supported on the fabric guideway 271.

At about the time the elements are in the position shown in Fig. 33, the main cam shaft 80 is shifted to the left to the normal knitting position, and the pendants 216 and instep bars 224 are wholly disconnected from their vertical and in and out cam motions, being latched in their normal inoperative position.

The shape and relationship of the various cams on the subsidiary cam shaft 270 which are necessary to give the various movements to the instep points, are shown in Figs. 34, 35, 36 and 37, the same figures showing the face cams on the disks 435 and 436 comprising the instep shift cam tracks 440, 446 and 443. The cams of these figures are all shown in the position they would occupy just prior to couliering or yarn sinking, with the shift roller 434 in its position after the latch lever 450 (Figs. 1 and 15) has permitted them to move inwardly.

Fig. 34 shows the up-and-down motion loop-taking cam 286 and Fig. 35 the in-and-out motion loop-taking cam 290, both figures showing the shift roller 434 as having moved inwardly to engage with the shift cam track 446, the levers associated with the up-and-down loop-taking motion is shown in dotted lines. As the parts are shown, therefore, rotation of the shift cam disk 436 will cause the shift roller 434 to contact the shift cam track 446, the incline of which will shift the cams to the right (Fig. 1) and so cause the shift rod 296, inside the cam shaft 270, to move to the right from the position shown in Fig. 1, thereby causing the up-and-down cam 286 to be aligned with the roller 306 of the up-and-down motion lever 298, at the same time aligning the in-and-out motion cam 290 with its roller 314 of the in-and-out motion lever 310. At the same time the roller 334 drops off the disk 338, causing the in-and-out motion link 322 with which it is associated

to encompass the pin 326 in the in-and-out motion lever 328, while the cam 410 is aligned with the right hand follower 404 (Fig. 1) of the latch lever 394.

Upon subsequent rotation of the cam shaft 270 with the cams 286, 290, 336 and 410 (understanding that all these cams are now under their respective operating levers, with the pin 332, associated with the link control roller 334 in line with its cam 336), the rise 37a of the cam 410 (Fig. 34) will remove the screw 398 of the lever 394 from under the extension 400 of one of the supporting levers 220, and at the same time remove its screw 418 (Fig. 2) from contact with the lever 422, so that the roller 314 will rest against the outer periphery of the cam 290 and the roller 306 will rest against the relatively low surface of its cam 286, with the roller 334 (Fig. 35) against the lowest portion of its cam 336, so that the hanger link 322, with which this control lever is associated, encompasses the pin in the lever 328.

As shown in Fig. 34, rotation of the cam shaft until the high point of the cam 286 (at line 18) is under the roller 306 raises the up-and-down lever 298, thereby raising the instep points 228 into the position shown in Fig. 18, while the latch lever 394 rides on the constant radius portion of its cam 410.

Considering now Fig. 35, it will be seen that rotation to the position line 18 will cause the roll 314 and lever 310 to drop onto the low portion of their cam 290 to move the points 228 from their idle position at the back of the needles to the position shown in Fig. 18.

Continued rotation to position 19 (Figs. 34 and 35) lowers the up-and-down motion (Fig. 32), at which position the needles are pressed in the points, as shown in Fig. 19. Such rotation does not affect the lever 394 or the pin 332.

Continued rotation to position 20, lowers the points and holds them pressed against the needles as shown in Fig. 20, at about which time the pin 332 commences to rise on its cam 336, without however disturbing the contact of its link 322 with the pin in the lever 328.

Continued rotation to position 21, raises the points to the position shown in Fig. 21, without moving the points horizontally; the relative movement that has taken place between the points and the needles, as shown in Fig. 21, is the result of the normal falling away of the needles from the points, as is common whenever the needles are functioning with the points to remove loops from them.

Continued rotation of the cam shaft to position 22, does not raise the points appreciably, but does operate by the engagement of the lever 508 with the high portion of its cam 518 and consequent shift of the rock shaft 496 and guide members 494 to shift the point bars 224 so that the points may pass between the needles, the rise between position lines 21 and 22 (Fig. 35) so moving them that when the operating parts are at position 22 (Fig. 35), the points are in the position shown in Fig. 22. About this time, the pin 332 has been lifted to the high position of its cam 336, so that the link 322, with which it is associated, is lifted clear of the pin in the lever 328. The pendants 216 and point bars 224 thereafter are not controlled horizontally so that the counterweight and take-up strap 392 can operate to tension the points away

from the needles against the heel fabrics which are now being knitted on the heel needles.

Continued rotation to position 23 (Fig. 34) lowers the points in back of the needles, as shown in Fig. 23, and while the cam 290 (Fig. 35) continues to act on the roll 314 of the lever 310, this movement does not affect the points or their operating mechanism, as the connecting link 322 is free of the pin in the lever 328.

Continued rotation to position 24 (Fig. 34) merely holds the points at about the level shown in Fig. 23 to permit the knockover bits to come in and engage with the fabric, as shown in Fig. 24.

The rotation of the cam shaft to position 25 raises the points into the position shown in Fig. 25. At this time, the follower 404 of the lever 394 (Fig. 34) drops off its cam 410 so that the subsequent raising of the in-and-out and up-and-down levers by bumps on their respective operating cams, permits the locking lever 394 to swing inwardly to engage the screws 398 and 418 (Fig. 3) respectively with the extension 400 and lug 420 to lock both motions in their idle position.

At this time, the cam 444 acts on the roller 442 (Figs. 15 and 35) to rock the shift lever 430 outwardly, the latch 452 then falling into position and thereby permanently locking the lever 430 in its fully retracted position with the shift roller 434 engaging in the neutralizing cam track 443 to shift the disks 440 and 444 and the rod 296 to their normal inoperative position, and to disconnect the cams 286, 410, 290 and 336 from their associated levers. The subsequent rotation of the cam shaft will leave the motions in their idle positions, with the roller 334 (Fig. 35) again on its idling disk 338.

The knitting of the stocking blank now continues with the knitting of the heel fabric which is pressed off, and a few ravel courses of sole fabric are formed as indicated generally in Figs. 26 and 27.

The instep shift mechanism is now again rendered operative by the engagement of a low bump on the pattern chain 135 with the instep pattern lever 466, which operates through connections above described, to permit the inward movement of the shift lever 430 and shift roll 434 into engagement with the cam track 440 to move the shift rod 296 and instep cams controlled thereby to the left from the neutral position shown in Fig. 1. This movement of the shift lever 430 is timed to take place after the needles are raised into their clear position from the position shown in Fig. 27. The movement of the shift rod 296 to the left, operates to shift the cam 288 into alignment with the roller 308 on the instep vertical motion cam lever 298, to position the cam 292 in alignment with the roller 316 on the instep forward and back motion cam lever 310, to position the cam 412 in alignment with the right hand follower 404 of the latch lever 394, and to move the disk 338 out from under the roll 334 on the link control lever 330, so that the link 322 is permitted to drop into engagement with the pin on the lever 328 to operatively connect the pendants 216 to the instep forward and back cam motion. Immediately upon the movement of the shift rod 296 to its operative position to the left, the fork 404 of the latch lever 394 is engaged by the inclined portion of its cam 412 (Fig. 36) to unlock the instep cam motion, so that the subsequent rotation of 75

the subsidiary cam shaft 270 can operate to return the instep fabric to the needles.

As the rod is shifted to its operative position to the left, the main cam shaft 80 of the machine 5 also is shifted to the right to its usual narrowing position by means of the usual shift mechanism controlled from the pattern chain of the machine.

The continued rotation of the subsidiary cam 10 shaft 270 until the position line 28 (Fig. 36) is under the roller 308, will cause a lifting of the points as shown in the corresponding Fig. 28, while the roller 316 (Fig. 37) commences moving down its incline, and so causes the instep 15 points 228 to move toward the needles.

Continued rotation of the cam shaft 270 to position 29, completes the horizontal movement of the points toward the needles, as shown in Fig. 29, and at the same time commences the 20 downward movement of the points while the needles in their regular narrowing movements are also moving downward.

Continued rotation of the cam shaft 270 to position 30, lowers the points to their lowest 25 position without moving them in or out, as shown by the cam outlines of Figs. 36 and 37, so that at position 30 the elements are as shown in Fig. 30.

Continued rotation to position 31, causes the 30 points and needles to move toward each other and so engage to a transfer position shown in Fig. 31.

Further rotation continues the lifting of the 35 points, while the needles are rising, without relative movement between the points and the needles, to position 32, thereby bringing the needles up through the loops held by the points (Fig. 32).

Rotation to position 33, withdraws the points 40 from the loops during their continued upward movement while the needles continue their upward movement to the position shown in Fig. 33.

Further rotation causes the points to continue 45 their upward movement, followed by a movement over and to the back of the needles, the path of the points being about as shown in dot-and-dash lines, Fig. 33. About this time the end of the lever 394 (Fig. 36) drops off its cam 412, while the roll 308 of the up-and-down motion moves 50 downwardly and the roller 316 on the instep in-and-out cam lever 310 moves onto an inclined portion of its cam 292, so that the stop screws 398 and 418 controlled by the latch lever 394 can again lock the instep cam levers 298 and 310 into 55 their inactive position. At the same time, a cam 338' (Fig. 1) on the face of the disk 338 engages the roller 334 to raise the link motion lever 330, so that the link 322 is disconnected from the lever 328, while the pin 526 acts to unlock the 60 latch 528 (Figs. 1 and 15) to permit the lever 302 to return the instep bar lateral shift and aligning levers 494 to their low position as shown in solid lines (Figs. 2 and 17). Also, about this time, the cam 444 acts on the roller 442 (Figs. 65 15 and 35) to move the roller shift lever 430 outwardly and so aligns the shift roller 434 with the neutralizing cam track 443, where it is latched into position so that upon subsequent rotation 60 of the cam shaft 270, the disks 435 and 436 with the shift rod 296 are shifted to the right, thereby taking the cams 288, 292 and 410 out of action and again placing the roller 334 (Fig. 37) on its idling disk 338.

The operation of applicant's machine to completely knit a full-fashioned stocking blank as

one continuous operation, may be described as follows: It may be assumed that the previous set has been cast off in the usual manner by the failure of a carrier to feed yarn during the last Coulier stroke, so that the completed stocking blanks are permitted to slide down the inclined portion of the fabric guideway or chute 271 into proper receptacles. The yarn carriers are now placed in action again to feed yarn, while at the same time one of the high bumps such as indicated at 471 (Fig. 12) on the pattern chain 135 moves under the actuating portion of the welt pattern cam lever 566 operating, as above described, to move the subsidiary cam shaft 270 and welt cams supported thereon to the left into operating position to form the initial or setting-up course of welt fabric. The movement of the pattern chain lever 566 acts also to render the loose course mechanism operative to insure the proper cooperation of the needles during the formation of the setting-up course, as above described. At the completion of the initial or setting-up course, the racking of the pattern chain 135 operates by moving the high bump referred to, from under the extension 568 of the pattern chain lever 566, to permit the return of the several cooperating mechanisms to inoperative position, the welt hooks now being positioned to the back sides of the needles and under the influence of their take-up tensioning strap or chain 392. During the continued knitting of the welt, the welt wires may be laid in along the length of the machine, and are automatically released through connections from the pattern chain as in applicant's copending application Serial No. 726,285 above referred to. After a sufficient amount of welt fabric has been knitted, the continued racking of the pattern chain will cause a relatively low bump such as that shown at 469 in Fig. 12, to engage beneath the extension 568 of the pattern chain lever 566, causing the cam shaft 270 and welt cams supported thereon, to be shifted to the right to close the welt, and thereafter to move the welt hooks away from the machine to an inoperative position.

The take-up straps connecting the welt wires to the usual fabric take-up roll 265 may now be wholly disconnected, allowing the fabric to lie loosely on the guideway 271, inasmuch as during the continued operation of the machine, applicant's notched knockover bits 72 will have the necessary take-up action to force the newly knitted fabric along the back line of the needles. The completed welt thus formed is designated at 670 in Figs. 6 and 7.

The knitting now proceeds in the usual manner, the narrowing machine operating first to form the leg narrowings 672, and thereafter the calf narrowings 674. It will be understood that the operation of the narrowing machine during this portion of the knitting is controlled in the usual manner from the pattern chain of the machine.

Before the point is reached in the knitting at which the heel flaps are to be formed, the narrowing machine is locked out of operation. The operator will also have shifted the relative positions of the instep bars and welt bars to bring the instep bars into operating position on their hanging frames 216.

Continued racking of the pattern chain now causes a high bump such as that illustrated at 471 in Fig. 12, to engage beneath the instep pattern cam lever 466 to shift the rod 296 and instep cams controlled thereby, to the right into oper-

ating position to cause the fabric loops forming the instep portion of the fabric, to be lifted out of engagement with and to the back sides of the needles. At the same time a bump on the narrowing chain operates the usual pattern narrowing control lever (not shown) to shift the main cam shaft 80 of the machine to the right to the usual narrowing position, so that the needles, sinkers and knockover elements will have their usual narrowing motions during the operation of the instep bars, to remove the instep loops from the needles. The next racking of the pattern chain will then operate to disconnect the hanging frames 216 and instep bars 228 from their actuating cams, with the instep points and loops supported thereon located out of engagement with and to the back side of the needles where they are held under the tensioning strain provided by a weight attached to the take-up strap or chain 392. At the same time the main cam shaft 80 is again shifted to the left so that knitting of the heel flaps 676 may be continued in the usual manner. Then follows the formation of the heel narrowings 678, and finally the heel ravel pieces 680, after which the heel fabrics are cast off.

Next a number of ravel courses of sole fabrics are knitted. As previously set forth, a bump on the pattern chain is arranged to engage beneath the portion 130 of the pattern lever 126 to shift the knockover element cam roll 110 out of alignment with its usual operating cam 112, and to engage the latch 132 beneath the knockover element cam lever 100, so that during the formation of the first ravel course of sole fabric, the knockover elements are maintained in a fully retracted position. The subsequent engagement of the pattern lever with the high bump on the chain, then causes the knockover element cam roll 110 to be shifted still further to the right, and the latch 132 to ride out from under the cam lever 100, so that during the knitting of a plurality of succeeding courses, the knockover elements are spring-pressed yieldingly forward with their notched portions in engagement with the sinker bars of the first ravel course. The continued racking of the pattern chain then causes the actuating portion 130 of the pattern lever 126 to ride out from under the high bumps on the chain, thus permitting the return of the knockover element cam roll 110 to its normal operating position in engagement with its operating cam 112. At some point prior to the return of the instep loops to the needles, the narrowing machine is again locked out of operation.

After the knitting of the requisite number of ravel sole courses designated at 682, a low bump on the pattern chain engages the instep pattern lever 466 to shift the rod 296 and instep cams controlled thereby on the cam shaft 270 to the left, so that the hanging frames 216 and instep bars 228 are rendered operative to return the instep fabric loops to the needles. At the same time a bump on the pattern chain operates to shift the main cam shaft 80 to the right, so that the needles, sinkers and knockover elements may have imparted thereto their usual narrowing motions to cooperate with the motions of the instep bar as above set forth. At the completion of the transfer operation, the instep bars are moved away from the machine, and the main cam shaft 80 is again shifted to its normal operating position for continued knitting of the

foot portion of the fabric. During the knitting of the next course, a partial loose course mechanism which may be of ordinary description, is rendered operative to form the sole fabric loops of this course loosely in order to mark the terminating course of the sole ravel fabrics in accordance with the usual practice, as indicated at 684 (see Fig. 6).

The narrowing machine is now again unlocked so that the knitting of the foot may proceed in the usual manner including the sole narrowings 686, the foot generally indicated at 688, and the toe 690 including the diamond point toe narrowings 692, and the toe ravel 694. The stocking is now complete with the exception of the usual joining operations which consist in first looping or otherwise joining together the inner heel wales 696 to the sole courses at the loose course 684, sewing together the selvage edges 698 of the leg and foot, and looping together the heel ravel 680 and toe ravel 694.

Figs. 61 and 62 of the drawings illustrate a slightly modified form of the invention in which a novel mechanism is provided for controlling the forward and back movements of the instep bar 224 and points 228 after the points 228 and instep fabric loops held thereon have been moved to the backs of the needles, as shown in Fig. 25, and during the subsequent knitting of the heel flaps to maintain the points in a predetermined relation to the needles during the forward and back movements thereof, and thus to prevent possible stretching, deformation, or possible breakage of the yarn forming the adjacent heel flap wales which might result from the application of a take-up tensioning strain, such as above described, in the knitting of certain types of yarn. The novel mechanism referred to compresses a link 701 which is arranged for operative engagement with the pin 702 of the welt in and out motion lever 370 above described, and is connected for continuous oscillatory forward and back motions with the needle motion of the machine. The link 701 is pivoted on the upper end of a lever 703 loosely pivoted on the shaft 144 and connected at its lower end by means of a link 704 to one of the needle in and out motion levers 81. A tension spring 705 tends normally to move the link 701 upwardly to engage an abutment 706 formed thereon with the pin 702. The link 701 is supported and guided at its forward end between two vertical bar guides 707 carried on pins 708 and 709 on one of the machine frames 66.

The position of the link 701 is controlled by means of a downwardly extending latch lever 710 secured at its upper end to a rock shaft 711 supported on the machine frame and at its lower end arranged for operative engagement with a laterally extending pin 712 on the link 701 to maintain the link normally in a depressed inoperative position against the pressure of its spring 705 in which the abutment 706 is held below and out of the path of movement of the lever 370 and pin 702.

Also secured to the rock shaft 711 is a cam lever 713 which is arranged, when the shift rod 296 and instep cams controlled thereby are shifted to the right, as above described, for removing the instep needle loops from the needles, for operative engagement with the operating cam 410 above described for controlling the operation of the latch lever 400. As best shown in Fig. 61 of the drawings, the cam 410 is provided with a

raised portion designated at 714 which operates at about the time the parts reach the positions shown in Fig. 25, and with the lever 370 in the dot and dash position shown in Fig. 61 to move the cam lever 713 and latch lever 710 out of engagement with the pin 712, so that the link 701 is permitted to move upwardly to engage the abutment 706 with the pin 702 on the lever 370.

The latch lever 710 is maintained in its forward inoperative position as the shift rod 296 and instep cams including the cams 410 are shifted to the left to their inoperative positions, and during the subsequent knitting of the heel flaps through connections which are preferably controlled from the pattern chain of the machine. These connections comprise a forwardly extending lever arm 715 on the rock shaft 711 which is connected by a downwardly extending link 716 to one end of a lever 717 pivoted at 718 against the under side of the table 65. A forward extension of the lever 717 is connected by another downwardly extending link 719 to one arm of a bell crank 730 mounted on the machine frame, the other arm of which is connected by a link 720 to a pattern chain lever 721 pivotally supported on the shaft 128 and having a downwardly extending bump engaging arm 722. A tension spring 723 secured at one end to the link 716 and at its other end to the table 65 acts on the connections above described including the rock shaft 711 to swing the cam lever 713 inwardly toward its cam 410, to swing the latch 710 into position over the pin 712 on the link 701, and to engage the extension 722 of the pattern chain lever 721 against the chain. The racking of the pattern chain 135 subsequent to the movement of the link 701 into operative position, as above described, operates to position the first of a series of bumps on the chain beneath the extension 722 of the pattern lever 721 to maintain the latch 710 in its forward inoperative position. The number of bumps employed in the series will correspond to the number of heel flap courses to be knitted. Thereafter, the pattern lever 721 is permitted to move inwardly, and the latch to swing rearwardly under the influence of the spring 723 disengage the link 701 from the pin 702 and lever 370 so that the pendants 216 and instep points carried thereon can swing outwardly to their normal inoperative position.

Figs. 63 to 66 inclusive of the drawings illustrate a novel and improved loop lifting implement which is particularly well adapted for use with applicant's instep bar 224 to insure the holding of the instep needle loops thereon during the knitting of the heel flaps and the initial ravel courses of sole fabric. Applicant's improved loop lifting point is designated at 724 in Figs. 63 to 66 inclusive, and follows the usual construction of these elements except that there is formed in the walls of the needle engaging side of the implement, a notch 725 which is preferably under cut slightly toward the tip of the point. The edges of the notched portions of the side walls are bevelled inwardly, as indicated at 726 in Figs. 63 and 65, in order that the points may be readily withdrawn from the loops after the transfer of the instep needle loop held thereon back to the needle.

The operation of applicant's improved loop lifting implements, when employed to remove and support the instep needle loops to the backs of the needles during the knitting of the heel flaps and sole ravel courses, and to thereafter transfer

the said loops back to the needles may be briefly described as follows:—The implements cooperate with the needles in the manner above described to engage upon the points and to raise the lifted loops above the tips of the needles. The needle loops placed in their usual position on the shanks of the loop lifting points as, for instance, in an ordinary narrowing operation, are located substantially opposite or above the notches 125. Owing to the tightness of the needle loop with relation to the cross sectional area of the loop lifting implements which will be relatively the same independently of the gage of the machine, the bar of yarn comprising the needle loop of the previously knitted course will be drawn tightly into the notch 125, as shown in Fig. 65, so that the fabric is positively held on the points during the subsequent knitting of the heel flaps and sole ravel courses, as illustrated in Figs. 26, 27 and 28. During the operation of transferring or returning the loop held on the implements back to the needles, as shown in Figures 31, 32 and 33, the tips of the needles moving relatively upwardly with relation to the loop lifting implements and pressed in the usual manner into the hollowed or grooved portions of the implements will pass under the bars of yarn formed by the needle loops of the previously knitted course so that these bars of yarn will be forced out of the notches 126 during the continued relative movement of the needles and points, as shown in Fig. 66, thus freeing the points from the fabric and permitting their removal as above described. The bevelled portions 125 of the notched walls of the implements serve to provide an adequate clearance to prevent possible catching of the fabric loops with the edges of the notches during this withdrawing movement. While applicant's improved loop lifting points have been specifically described and illustrated in connection with the operation of removing and thereafter returning the instep needle loops to the needles, it will be understood that these implements may be used with equally advantageous results for other loop lifting and transfer operations.

While the machine disclosed in the drawings including the several cooperating instrumentalities described and having the mode of operation set forth, illustrates a preferred embodiment of the applicant's invention including the several novel features thereof, it will be understood that the invention in its broader aspects is not limited to the specific construction and arrangement of the several cooperating elements set forth, and that certain of the instrumentalities shown may be modified or omitted without rendering the machine inoperative, or causing any loss of function or advantage which may be obtained from combinations embracing a smaller number of parts as specifically set forth in the claims.

Certain features of applicant's construction relating specifically to his improved loop lifting implement, have been made the subject-matter of a divisional application Serial No. 370,496, filed December 17, 1940.

The invention having been described, what is claimed is:

1. In a flat full-fashioned foot and leg knitting machine having knitting devices including a series of needles movable as a unit and yarn measuring sinkers, a cam shaft and connections therefrom for operating said knitting devices, a narrowing mechanism for the machine including a narrowing needle cam motion, an instep fabric supporting bar comprising a series of loop

lifting implements, cam means for imparting positioning movements in a horizontal plane and vertical movements to said instep bar in timed relation to said narrowing needle cam motion 5 to remove the instep needle loops from the needles and to position said implements and instep loops held thereon beyond the back line of the needles for subsequent knitting of the heel flaps, and means for placing said needle narrowing cam motion and instep cams in operation.

2. In a flat full-fashioned foot and leg knitting machine having knitting devices including a series of needles movable as a unit and yarn measuring sinkers, a cam shaft and connections 15 therefrom for operating said knitting devices, a narrowing mechanism for the machine including a narrowing needle cam motion, an instep fabric supporting bar comprising a series of loop lifting implements, cam means for imparting positioning movements in a horizontal plane and vertical movements to said instep bar in timed relation to said narrowing needle cam motion to remove the instep needle loops from the needles and to position said implements and instep loops held 20 thereon beyond the back line of the needles during subsequent knitting of the heel flaps, cam means for moving said instep bar in timed relation to said narrowing needle cam motion to return said instep loops to the needles, and means 25 for controlling the operation of each of said cam means and the narrowing needle cam motion co-operating therewith to remove and thereafter to return the instep loops to the needles.

3. In a flat full-fashioned foot and leg knitting 30 machine having a series of needles movable as a unit, a welt mechanism comprising welt loop taking and transfer elements, means for actuating said elements to take an initial course of loops of welt fabric and thereafter to transfer 35 said loops to the needles to close the welt, an instep fabric supporting mechanism comprising a series of instep loop lifting implements, means for actuating said loop lifting implements to take from the needles and to support the instep fabric 40 loops for the knitting of the heel flaps, and thereafter to return said instep loops to the needles, and pattern devices for controlling the 45 operation of each of said actuating means in accordance with a predetermined pattern of operation 50 of the machine.

4. A flat knitting machine having in combination, a series of needles movable as a unit and yarn measuring sinkers, a support, a series of loop lifting implements carried on said support, 55 welt loop taking and transfer elements carried on said support, means for relatively positioning said implements and elements on said support to position one or the other of said implements and elements alternatively in operating position 60 and for positioning the other of said implements and elements in inoperative position, means for actuating said support and said welt elements supported thereon to take and thereafter to transfer to the needles an initial course of welt 65 loops for forming a bight of welt fabric, and means for actuating said support and said loop lifting implements carried thereon to remove from the needles and thereafter to return there- 70 to selected needle wale loops.

5. In a flat knitting machine having a series of needles movable as a unit, a support, instep loop lifting implements carried on said support, welt loop taking and transfer elements carried on said support, means for actuating said support and 75 said welt elements supported thereon to take and

thereafter to transfer to the needles an initial course of welt loops for forming a bight of welt fabric, and means for actuating said support and instep loop lifting implements carried thereon to take from the needles the instep needle loops for the knitting of the heel flaps, and thereafter to return said instep loops to the needles.

6. In a flat knitting machine having a series of needles movable as a unit, a support, instep loop lifting implements carried on said support, welt loop taking and transfer elements carried on said support, means for positioning said instep implements and welt elements alternatively in operating position on said support, means for actuating said support and said welt elements supported thereon to take and thereafter to transfer to the needles an initial course of welt loops for forming a bight of welt fabric, and means for actuating said support and instep loop lifting implements carried thereon to take from the needles the instep needle loops for the knitting of the heel flaps, and thereafter to return said instep loops to the needles.

7. In a flat knitting machine having knitting devices including a series of needles movable as a unit, a welt hook bar comprising a series of welt hooks, an instep fabric supporting bar comprising a series of loop lifting implements, a hanging frame on which both of said bars are supported to move toward and away from the needles, and a vertically movable pivotal support for said frame.

8. In a flat knitting machine having knitting devices including a series of needles movable as a unit, a welt hook bar comprising a series of 35 welt hooks, an instep fabric supporting bar comprising a series of loop lifting implements, a hanging frame on which both of said bars are supported to move toward and away from the needles, a vertically movable pivotal support for 40 said frame, and means for positioning said welt bar and said instep bar alternatively in operating position on the frame.

9. In a flat knitting machine having knitting devices including a series of needles movable as a unit, a welt hook bar comprising a series of welt hooks, an instep fabric supporting bar comprising a series of loop lifting implements, a hanging frame on which both of said bars are supported to move toward and away from the 50 needles, a vertically movable pivotal support for said frame, means for positioning said welt bar and said instep bar alternatively in operating position on the frame, mechanism for imparting vertical and swinging movements to the frame and welt bar to take and thereafter to transfer to the needles an initial course of welt loops to 55 form the welt, mechanism for imparting vertical and swinging movements to the frame and instep bar to take from the needles the instep 60 needle loops for the knitting of the heel flaps, and thereafter to return said instep loops to the needles.

10. A flat full-fashioned foot and leg knitting machine having, in combination, a series of needles movable as a unit, a welt bar comprising a series of welt hooks, an instep bar comprising a series of loop lifting implements, a support on which said bars are carried, a movable supporting frame on which said support is pivotally 65 mounted, and means for maintaining said support in alternative positions with one or the other of said bars in operating position comprising cooperating stop members on the support and on the frame arranged to permit a limited rotation- 75

al movement of the support, and a toggle spring connection acting on said support.

11. A flat full-fashioned foot and leg knitting machine having, in combination, a series of needles movable as a unit, a welt bar comprising a series of welt hooks, an instep bar comprising a series of loop lifting implements, a support on which said bars are carried, a movable supporting frame on which said support is pivotally mounted, and means for maintaining said support in alternative positions with one or the other of said bars in operating position comprising cooperating stop members on the support and on the frame to limit the movement of the welt bar rearwardly and upwardly in operating position, and to limit the movement of the instep bar rearwardly and downwardly in operating position, and a toggle spring connection acting on said support.

12. A flat knitting machine having, in combination, a series of needles movable as a unit and yarn measuring sinkers, a welt bar comprising a series of welt hooks, an instep bar comprising a series of loop lifting implements, a support on which said bars are carried, a movable supporting frame on which said support is pivotally mounted and means for maintaining said support against rotational movement on said frame in alternative positions with one or the other of said bars in operating position.

13. A flat knitting machine having, in combination, a machine frame, a series of needles movable as a unit and yarn measuring sinkers, a welt bar comprising a series of welt hooks, an instep bar comprising a series of loop lifting implements, a support for said bars, a supporting frame movable toward and away from the needles having a pivotal connection with said support arranged to permit axial movement of the support with relation thereto lengthwise of the needle series, means for securing said support against rotational movement on said frame in alternative positions with one or the other of said bars in operating position, and cooperating guides and guiding members carried respectively on the support and on the machine frame for registering the support and bars secured thereto axially with relation to the needle series.

14. A flat knitting machine having, in combination, a machine frame, a series of needles movable as a unit and yarn measuring sinkers, a welt bar comprising a series of welt hooks, an instep bar comprising a series of loop lifting implements, a support for said bars, a hanging frame movable toward and away from the needles having a pivotal connection with said support arranged to permit axial movement of the support with relation thereto, means for locking said support against rotational movement on said frame in alternative positions with one or the other of said bars in operating position, guides rigidly secured to the support, cooperating guide members on the machine frame arranged for engagement with said support guides to position the support and welt bar axially for cooperative engagement with the needles, and instep bar guide members on said frame arranged for engagement with said support guides for positioning said instep bar and support axially in cooperative relationship to the needles.

15. A flat knitting machine having, in combination, a machine frame, a series of needles movable as a unit and yarn measuring sinkers, a series of instrumentalities cooperating with the needles to transfer loops to and from the

needles, a bar to which said instrumentalities are rigidly secured, a support on which said bar is supported for movement into and out of cooperating relationship to the needles and arranged to permit movement of said bar with relation to the support lengthwise of the needle series, guides secured to move with the bar, cooperating guide members on the machine frame arranged for engagement with the bar guides to register said instrumentalities in line with the needles, separate guide members on the machine frame for engagement with said bar guides to align said instrumentalities between the needles, and means for positioning one or the other of said guide members alternatively for engagement with the bar guides.

16. In a flat full-fashioned foot and leg knitting machine having a machine frame, a series of needles movable as a unit and yarn measuring sinkers, the combination of an instep bar comprising a series of loop lifting points, a supporting frame for said bar movable toward and away from the needles, and arranged to permit movement of the instep bar thereon lengthwise of the needle series, guides secured to move with the bar, cooperating guide members on the machine frame for registering said instep bar lengthwise with relation to the needle series, mechanism for moving said frame and instep points toward and away from the needles to position the instep needle loops on said points to the back sides of the needles and subsequently to return the loops to the needles, and connections acting in timed relation to said mechanism for shifting said guide members and the points controlled thereby a half needle index for movement of the points and instep loops held thereon forwardly between and to the back sides of the needles.

17. In a multiple section flat full-fashioned foot and leg knitting machine having a machine frame, needles movable en masse and yarn measuring sinkers, the combination of an instep bar comprising a series of loop lifting points associated with each section of the machine, a supporting frame for said bar movable toward and away from the needles, and arranged to permit movement of the instep bar thereon lengthwise of the needle series, guide members on the machine frame to engage with and register the instep bar associated with each section lengthwise with relation to the needle series, mechanism for simultaneously moving the frames and instep points associated with each section toward and away from the needles to position the instep needle loops on said points to the back sides of the needles for the knitting of the heel flaps, and connections acting in timed relation to said mechanism for moving said guide members to shift simultaneously the point bars for the several sections one-half a needle index for movement of the points and instep loops held thereon forwardly between and to the back sides of the needles.

18. A multiple section full-fashioned foot and leg knitting machine having, in combination, for each section a series of needles movable as a unit, yarn measuring sinkers, an instep bar comprising a series of loop lifting points, a support on which the bar is movable lengthwise of the needle series, means for moving the support and points associated with each section toward and away from the needles to remove the instep needle loops beyond the back line of the needles and thereafter to return the instep needle loops to the needles, means for registering each of said

instep bars lengthwise with relation to the needle series comprising a control rod, guides on said rod for engaging with the instep bars associated with each of the several sections, and means for controlling the axial position of said rod to register the points for engagement with the needles, and for shifting the point bars lengthwise for movement of the points between and beyond the back line of the needles.

19. A flat full-fashioned foot and leg knitting machine having, in combination with a series of needles movable as a unit and yarn measuring sinkers, an instep bar comprising a series of loop lifting points, guide members associated with said bar, a support on which said bar is free to slide lengthwise of the needle series, cam actuated means for moving said support into and out of operative engagement with the needles to remove beyond the back line of the needles and thereafter to return the instep needle loops to the needles, guides arranged for engagement with said guide members to position the instep bar lengthwise of the needle series, and cam actuated means for moving said guides to register the points with the needles, to shift the point bar lengthwise for movement of the points between and beyond the back line of the needles, and thereafter to again shift the point bar to register the points with the needles.

20. A flat full-fashioned knitting machine having, in combination with a series of needles movable as a unit and yarn measuring sinkers, a welt mechanism comprising welt set-up and transfer elements, and actuating connections therefor operating in timed relation to the movements of the needles to set up and thereafter to close the welt, a loose course mechanism for the machine, pattern mechanism for the machine including a pattern chain, a welt pattern lever and connections rendered operative by a high bump on the chain for rendering said welt actuating connections operative to set up the welt on said elements, and by a low bump on the chain to close the welt, and connections from said welt pattern lever rendered operative only by the engagement of the pattern lever with a high bump on the chain to actuate said loose course mechanism.

21. A flat knitting machine having knitting devices including a series of needles movable as a unit, a cam shaft and connections therefrom for operating said knitting devices, a welt mechanism comprising welt loop taking and transfer elements operable to take an initial course of loops of welt fabric and thereafter to transfer said loops to the needles to close the welt, an instep fabric supporting mechanism comprising a series of instep loop lifting implements operable to take from the needles and to support the instep fabric loops during the knitting of the heel flaps and thereafter to return said instep loops to the needles, a subsidiary cam shaft, and cams on said shaft for actuating each of said mechanisms.

22. A flat knitting machine having knitting devices including a series of needles movable as a unit, a cam shaft and connections therefrom for operating said knitting devices, a welt mechanism comprising welt loop taking and transfer elements operable to take an initial course of loops of welt fabric and thereafter to transfer said loops to the needles to close the welt, an instep fabric supporting mechanism comprising a series of instep loop lifting implements operable to take from the needles and to support the instep fabric loops during the knitting of the heel flaps

and thereafter to return said instep loops to the needles, a subsidiary cam shaft, cams on said shaft for actuating each of said mechanisms, and means for selectively throwing said mechanisms into and out of operation.

23. In a flat full-fashioned foot and leg knitting machine having knitting devices including a series of needles movable as a unit, a cam shaft and connections therefrom for actuating the knitting devices, a welt mechanism comprising welt loop taking and transfer elements, an instep fabric supporting mechanism comprising a series of instep loop lifting implements, a subsidiary cam shaft, welt set-up cams thereon for actuating said welt mechanism to take an initial course of welt loops, welt transfer cams on said subsidiary cam shaft for actuating said welt mechanism to transfer said loops to the needles to close the welt, control means for moving said cam shaft in opposite directions to render one or the other of said welt taking and transfer cams operative, instep loop taking cams on said subsidiary cam shaft for actuating said loop lifting implements to take from the needles and to support the instep fabric loops for the knitting of heel flaps, instep return cams on said subsidiary cam shaft for actuating said implements to return the loops to the needles, a control shaft connected to move said instep cams axially of said subsidiary cam shaft, and control means for moving said control shaft in opposite directions to render one or the other of said instep loop taking and return cams operative.

24. In a flat full-fashioned foot and leg knitting machine having knitting devices including a series of needles movable as a unit, a cam shaft and connections therefrom for actuating the knitting devices, a welt mechanism comprising welt loop taking and transfer elements, an instep fabric supporting mechanism comprising a series of instep loop lifting implements, control cams for said welt elements including welt setting-up cams and transfer cams, control cams for said loop lifting implements including instep loop lifting cams and instep loop return cams, a subsidiary cam shaft on which all of said cams are keyed to rotate, and on which one of said welt and instep sets of cams are secured against axial movement relatively thereto, a control shaft journaled within the cam shaft and connected to control the axial position of the other of said sets of welt and instep cams, control devices for controlling the axial position of each of said subsidiary cam shaft and control shaft for throwing each of said cams into and out of operation.

25. A flat knitting machine having knitting devices including a series of needles movable as a unit, a cam shaft, and connections therefrom for operating said knitting devices, fabric setting-up mechanism comprising hooks movable to receive a setting up course of fabric loops, an instep fabric supporting mechanism comprising a series of instep loop lifting implements operable to take from the needles and to support the instep fabric loops during the knitting of the heel flaps, and thereafter to return said instep loops to the needles, a subsidiary cam shaft, and cams on said shaft for actuating each of said mechanisms.

26. In a flat full-fashioned foot and leg knitting machine having knitting devices including a series of needles movable as a unit, an instep fabric supporting bar comprising a series of loop lifting implements, means for relatively

moving said instep bar and needles to remove the instep needle loops from the needles and to position said implements and instep loops held thereon beyond the back line of the needles, and means for imparting forward and back movements to said implements in timed relation to the needle motion to maintain said implements in a substantially constant relationship to the needles closely adjacent the backs thereof during the subsequent knitting of the heel flaps.

27. In a flat knitting machine having knitting devices including a series of needles movable as a unit, an instep fabric supporting bar comprising a series of loop lifting implements, a vertically movable pivotal support for the hanging frame, means for imparting vertical and swinging movements to the hanging frame and instep bar supported thereon to take the needle loops from the needles, and thereafter for positioning said loops beyond the backs of the needles, means for imparting forward and back movements to said hanging frame and instep bar in timed relation to the needle motion to maintain said implements in a substantially constant relationship to the needles closely adjacent the backs thereof during the subsequent knitting of the heel flaps, and means for imparting vertical and swinging movements to said hanging frame and instep bar to return said instep loops to the needles.

28. In a flat knitting machine having knitting devices including a series of needles movable as a unit, an instep bar comprising a series of loop lifting implements, a pattern mechanism for the machine, cam means controlled thereby for imparting forward and back and vertical movements to said bar to remove and to position the instep needle loops on said implements beyond the back line of the needles, means for imparting forward and back movements to said bar in timed relation to the needle motion to maintain said implements in a substantially constant relationship to the needles closely adjacent the backs thereof, a cam actuated control device for rendering said latter means operative, and a pattern actuated control to render said latter means inoperative upon casting off of the heel flaps.

29. In a flat knitting machine having knitting devices including a series of needles movable as a unit, an instep fabric supporting bar comprising a series of loop lifting implements, a hanging frame on which said bar is supported to move forward and back in the direction of take-up toward and away from the needles, and a vertically movable pivotal support for said hanging frame.

30. In a flat knitting machine having knitting devices including a series of needles movable as a unit, an instep fabric supporting bar comprising a series of loop lifting implements, a hanging frame on which said bar is supported to move forward and back in the direction of take-up toward and away from the needles, a vertically movable pivotal support for said hanging frame, and means for imparting vertical and swinging movements to said hanging frame and instep bar carried thereon to remove from the needles the instep needle loops for the knitting of the heel flaps, and thereafter to return said instep loops to the needles.

31. In a flat knitting machine having knitting devices including a series of needles movable as a unit, an instep fabric supporting bar comprising a series of loop lifting implements, a swing-

ing frame on which said bar is supported to move forwardly and back in the direction of take-up toward and away from the needles, a vertically movable pivotal support for said swinging frame, and means for imparting vertical and swinging movements to said frame and instep bar carried thereon to remove from the needles the instep needle loops for the knitting of the heel flaps, and thereafter to return said instep loops to the needles.

32. In a flat knitting machine having knitting devices including a series of needles movable as a unit, an instep fabric supporting bar comprising a series of loop lifting implements, a swinging frame on which said bar is supported to move forwardly and back in the direction of take-up toward and away from the needles, a vertically movable pivotal support for said swinging frame, means for imparting vertical and swinging movements to said frame and instep bar carried thereon to remove from the needles the instep needle loops for the knitting of the heel flaps, and thereafter to return said instep loops to the needles, pattern mechanism for the machine, and connections therefrom for instituting each of said instep loop removal and return operations.

33. In a flat knitting machine having knitting devices including a series of needles movable as a unit, a welt hook bar comprising a series of welt hooks, an instep fabric supporting bar comprising a series of loop lifting implements, a swinging frame on which both of said bars are supported to move toward and away from the needles, a vertically movable pivotal support for said frame, and means for imparting vertical and swinging movements to said frame and welt bar supported thereon to turn the welt, and means for imparting vertical and swinging movements to said frame and instep bar carried thereon to remove from the needles the instep needle loops for the knitting of the heel flaps, and thereafter to return said instep loops to the needles.

34. In a flat knitting machine having knitting devices including a series of needles movable as a unit, a welt hook bar comprising a series of welt hooks, an instep fabric supporting bar comprising a series of loop lifting implements, a swinging frame on which both of said bars are supported to move toward and away from the needles, a vertically movable pivotal support for said frame, actuating means for imparting vertical and swinging movements to said frame and welt bar supported thereon to turn the welt, actuating means for imparting vertical and swing-

ing movements to said frame and instep bar carried thereon to remove from the needles the instep needle loops for the knitting of the heel flaps, and thereafter to return said instep loops to the needles, and pattern mechanism for rendering the actuating means operative to effect each of said welt turning and instep loop removal and return operations.

35. In a flat full-fashioned foot and leg knitting machine having a series of needles movable as a unit, a welt mechanism including actuating means operable to automatically turn the welt, instep fabric supporting mechanism including implements operable to remove a series of instep loops from the knitting line of the active needle series, and subsequently to return said instep loops to the knitting line of the active needle series, actuating means for said instep fabric supporting mechanism, and pattern devices for controlling the operation of each of said actuating means in accordance with a predetermined pattern of operation of the machine.

36. In a flat full-fashioned foot and leg knitting machine having a series of needles movable as a unit, a welt mechanism including actuating means operable to automatically turn the welt, automatic mechanism for joining a foot portion to the heel and instep portions including means automatically operable for supporting the instep loops in inactive position during the knitting of the heel portions, and means for thereafter continuing the knitting upon the instep and adjacent needles to knit the foot, and pattern means for instituting the operation of each of said automatic mechanisms in accordance with a predetermined pattern of operation of the machine.

37. In a flat full-fashioned foot and leg knitting machine having a series of needles movable as a unit, a welt mechanism including actuating means operable to automatically turn the welt, automatic mechanism for joining a foot portion to the heel and instep portions including means automatically operable to discontinue knitting on the instep needles during the knitting of the heel portions and for supporting the terminal instep wale loops in inoperative position, and means for returning the instep needles to active operation to continue the knitting upon the instep and adjacent needles to knit the foot, and pattern means for instituting the operation of each of said automatic mechanisms in accordance with a predetermined pattern of operation of the machine.

MAX C. MILLER.
